UNITED STATES PATENT OFFICE.

FRANK C. MARQUARDT, OF BROOKLYN, NEW YORK. ASSIGNOR TO AMERICAN BANK
NOTE COMPANY, OF NEW YORK, N. Y., A CORPORATION OF NEW YORK.

MULTICOLOR-PRINTING MACHINE.

Application filed February 9, 1922. Serial No. 535,162.

To all whom it may concern:

Be it known that I, FRANK C. MARQUARDT, a citizen of the United States, residing at the borough of Brooklyn, in the city of New York, county of Kings, and State of New York, have invented certain new and useful Improvements in Multicolor-Printing Machines, of which the following is a specification, reference being had therein to the accompanying drawings, which form a part thereof.

My invention relates to multicolor printing machines, and more particularly to a type thereof embodying a plurality of plate or form cylinders grouped about a cylinder having an offset planographic surface or surfaces upon which a completed design, different portions of which are carried by the several cameo plates upon said plate cylinders, is collected in different colors preparatory to the making of an imprint of the completed multicolor or chromatic design at a single impression.

Machines of the character to which my invention relates are especially adapted for making safety tints for various negotiable, or commercial, instruments and are not suitable for art work wherein the different color pigments are associated and superimposed one upon another in a manner to secure different color effects. In producing safety tints, however, light impressions are made from line designs, or designs having vignette effects, which serve as a background for other impressions.

In a machine designed for making such tints, the ink lines in different colors must have absolute register one with the other, notwithstanding that the design is built up from a number of fragmentary portions upon different plates, and in a plurality of different colors. The colors, while being only applicable to the plates along straight lines extended circumferentially of the plate cylinder, are distributed throughout the design by limiting the printing areas of said plates and employing ink founts associated with each plate capable of severally applying a different color thereto within certain definite limitations controlled by the structure of the fount in co-operation with the raised or cameo design upon the plate.

In a printing machine embodying my invention, the rubber blanketed planographic cylinder and the associated plate cylinders

adapted to receive the cameo printing plates bearing different portions of the design, are adapted to rotate continuously while the machine is in operation and at the same peripheral speed, said planographic cylinder being adapted to carry a plurality of blankets, and said plate cylinders being of a diameter to require two revolutions thereof to one revolution of said planographic cylinder. The plate cylinders are positively moved toward the planographic cylinder, but are acted upon by springs having a normal tendency to move them away from said cylinder, the construction being such that the pressman may cause all operative plate cylinders to move away from the planographic cylinder under the control of said springs, and to cause simultaneous movement of the impression cylinder away from the planographic printing cylinder.

The mechanism for applying power to move each plate cylinder with relation to the planographic cylinder is so constructed that it may be so set as to cause each plate cylinder to recede from the planographic cylinder during a portion of each revolution, to permit all plate cylinders to remain in the inking relation to said planographic cylinder at all times; or to cause any or all of said cylinders to be held out of the operative relation to said planographic cylinder. Hence during the make-ready of a machine it may be so set that any of the plate cylinders may be selectively used in transferring designs onto the planographic cylinder, the permanent throwing out or disengagement of one plate cylinder having no effect upon the control means as to other cylinders.

The various mechanisms for controlling the power for thus actuating the plate cylinders and the impression cylinder operate continuously while the machine is in operation, the application of this power to the cylinders being through an intermediate mechanism normally under no load so as to permit the setting thereof by hand without difficulty.

When but a single blanket is used upon the planographic cylinder, the machine may be so set as to cause the plates upon any or all of the plate cylinders to apply the ink design to this blanket. When two blankets are used, the machine may be so set as to cause the plates upon some of the plate cylinders to transfer a completed design to one of said blankets, while the plates upon other

- of said cylinders will be caused to transfer a completed design upon the other blanket, thus permitting two jobs requiring different designs in different colors to be 5 done on the machine at the same time, the machine acting as a non-perfected machine. Or if desired, by feeding sheets to one of the blankets upon said planographic cylinder only, the design from the other blanket 10 may be transferred to the impression cylinder and thus permit the machine to be used as a perfecting machine without the employment of a separate inking mechanism in relation to the impression cylinder.
- 15 I associate with said impression cylinder, however, a plate cylinder and its associated inking mechanism, which may be used either for the purpose of permitting greater intricacy in the design impressed upon the 20 paper by said impression cylinder when the machine is in operation as a perfecting machine, due to the capability of utilizing any of the four cylinders associated with the planographic cylinder in addition to the 25 plate cylinder co-operating with said impression cylinder, for transferring portions of a design to said impression cylinder, or of permitting the transfer of a design to said impression cylinder independently of the 30 planographic cylinder.
- 35 In this manner the machine is adapted to an unlimited range of work and the use of any desired combination of colors, and for use either in perfecting or non-perfected work.
- 40 The throw-off mechanism operative upon the impression cylinder is also operative upon its plate cylinder and its associated inking mechanism.
- 45 Associated with each plate cylinder is an inking mechanism consisting of two or more ink founts each adapted to apply an ink of one color to a doctor or doctor roll which applies it in stripes to distributing rolls common to all of the founts, said distributing rolls ensuring a proper cutting and distribution of the ink, and when desired, a proper blending of adjacent colors to get chromatic effects in the imprint before it is finally applied by the inking rolls to the cameo plate upon the plate cylinder with which the inking mechanism and the ink founts are associated.
- 55 While the distributing rolls are carried by a frame movable in relation to the ink founts and acted upon by springs so as to maintain the inking rolls in the proper inking relation to the plates upon the plate cylinder, said frame is adapted to have movement with the plate cylinder toward and from the planographic cylinder so as to permit a continued inking of the plates even though the plate cylinder be out of engaging relation to the blanket of the planographic 60 cylinder. Means, however, are provided

whereby in the event of one of the plate cylinders being permanently thrown out of engagement with the planographic cylinder, the doctor or doctor rolls may be made inoperative to transfer ink from the fount to 70 the distributing rolls, thus permitting any plate cylinder to remain inoperative, without increasing the strength of the ink film upon the distributing rolls and without the necessity for cleaning out the ink founts, in 75 the event that it is desired to temporarily discontinue its use. The control of the doctor or doctor rolls associated with the inking mechanism of each plate cylinder may be either manual or automatic.

80 In a machine embodying my invention, the use of a plurality of ink founts permits exactitude of register of the differently colored inked portions of the design upon each plate, and also exactitude in the register 85 of the portions of the design upon one plate with portions upon other plates, notwithstanding that a plurality of different colors may be used in the founts associated with each plate cylinder.

90 In some lines of work it is desirable to mix or blend inks of different colors upon the mixing and distributing rolls before inking the plates, means being provided in connection with the inking mechanism for each 95 plate cylinder whereby the ink upon the distributing and inking rolls may be mixed to secure the desired chromatic effects. This means is not only independently controllable as to each plate cylinder, but may be so adjusted as to be totally inoperative so as to avoid the blending effect above referred to, or to increase the range of the blended portions of the design.

100 The blending rolls will not have any function in securing register of the inks for differently colored portions of the design, or in cutting the ink upon the distributing rolls, the axial movement of these blending rolls being solely for the purpose of securing a 110 uniform blending of the inks while upon the distributing and inking rolls and before application to the plates upon the plate cylinders.

115 To facilitate the make-ready of a machine, the inking mechanism associated with each of the plate cylinders including the ink founts, as well as the inking mechanism associated with the plate cylinder co-operating 120 with the impression cylinder, is so mounted as to be movable in its entirety into and out of the operative relation to its associated plate cylinder, the inking rolls and some of the distributing rolls being capable of independent movement with relation to 125 others of the distributing rolls, intermediate same and the ink founts, and being spring-pressed toward the plate cylinder to be inked thereby, thus permitting the entire inking mechanism to be moved away from the print- 130

ing couple when making ready for a run, while permitting the inking rolls to have movement with the plate cylinders independently of any movement of the remainder of 5 the inking mechanism.

The movement of the inking mechanism associated with the plate cylinders for inking the planographic offset cylinder is rectilinear, while the movement of the inking 10 mechanism associated with the plate cylinder for inking the impression cylinder for use in perfecting work, is rotative.

As a further facility during the make-ready, the feed shelf is so constructed as to 15 fold upon itself and be elevated so as to be entirely removed from its position adjacent the printing couple and thus permit free access thereto from both above and below the normal plane of this feed shelf.

20 While automatically acting means are provided for preventing actuation of the ductor or doctor rolls, in the event of the throw-off of any cylinder while the machine is running, this mechanism may, at the will 25 of the operator, be made inoperative so as to permit only a manual actuation of the means for making said ductor or doctor rolls inoperative, a condition growing out of the possibility of using one of the blankets upon 30 the planographic offset cylinder as a transfer surface for applying an inked design to the impression cylinder for perfecting work, and for using different designs upon different blankets.

35 The invention consists in a printing machine embodying therein the novel features of construction and combination of parts hereinafter set forth and described, and more particularly pointed out in the claims 40 hereto appended.

Referring to the drawings,

Fig. 1 is a side elevation of a machine embodying my invention, with the delivery portion thereof omitted;

45 Fig. 2 is a side view of said delivery end of the machine;

Fig. 3 is a diagrammatic showing of the printing couple, the plate cylinders associated therewith and the inking mechanisms 50 associated with said plate cylinders respectively;

Fig. 4 is a detail view of that portion of the feed shelf mechanism of the machine adjacent the printing couple;

55 Fig. 5 is a detail side elevation showing the throw-off mechanism and its controlling means, and the inking mechanisms associated with the plate cylinders operative upon the planographic cylinder;

60 Fig. 6 is a detail view upon an enlarged scale showing a portion of said mechanism operative in relation to one of the plate cylinders operative upon the planographic cylinder and to the impression cylinder and 65 its associated parts;

Figs. 7 and 8 are views upon an enlarged scale, illustrating the relation of parts with the throw-off mechanism as to one plate cylinder, when the machine is set to throw out said cylinder with each half cycle of 70 the planographic cylinder;

Figs. 9 and 10 illustrate a fragmentary portion of said mechanism showing the manner in which it is set to permit continuous engaging relation of the plates upon said 75 plate cylinder with the planographic cylinder until the throw-off mechanism is actuated, and the relation of parts after the actuation of said mechanism;

Fig. 11 is a perspective view of one of 80 the oscillating setting plates;

Fig. 12 is a detail view of one of the plate cylinders for inking blankets upon the planographic cylinder, and its associated inking mechanism on one side of the machine; 85

Fig. 13 is a view of the impression cylinder, the plate cylinder associated therewith, and the inking mechanism co-operating with 90 said plate cylinder;

Fig. 14 is a view of another of said mechanisms upon the other side of the machine, showing the actuating mechanism for the blending rolls;

Fig. 15 is a view in detail of a portion 95 of one of the inking mechanisms showing the mechanism operative upon the blending rolls thereof;

Fig. 16 is an end view of Fig. 15 upon a reduced scale; 100

Fig. 17 is a rear view of one of the upper inking founts and its appurtenant mechanisms;

Fig. 18 is a detail view of one end of the 105 planographic cylinder;

Fig. 19 is a detail view of one of the ductor roll mechanisms; and

Fig. 20 is a perspective view of two associated ink founts.

Like numerals refer to like parts throughout the several views.

In view of the complicated nature of the machine embodying my invention, in describing the machine, I will refer only in detail to those mechanisms which are necessary to a clear understanding of the invention, and omit specific reference to other mechanisms which are largely matters of design and require no special construction resulting in new functions in the machine. 115

In the machine of my invention, the printing couple consists of a planographic offset cylinder 20 having a plurality of rubber blankets 21 and 22, although if desired a continuous rubber surface may be used upon this cylinder, two blankets being used merely because of greater facility in securing and maintaining the desired printing surfaces. 125

Associated with the cylinder 20 is an impression cylinder 23 also provided with a 130

- rubber blanketed surface 24 so as to permit the use of this cylinder as a planographic offset cylinder for perfecting work when so desired. The blanket 24 extends about only 5 a portion of the periphery of the cylinder 23 to facilitate its being brought to and maintained in the desired condition, although as with the cylinder 20, this blanket may be a continuous surface, if so desired. 10 The cylinder 23 is of one-half the diameter of the cylinder 20 so as to make two revolutions to one of said cylinder 20. This permits the impression cylinder, when being used for perfecting work, to be inked from 15 one of the blankets upon the cylinder 20. The members of the printing couple are driven in unison by means of intermeshing gears in a manner common in this art, such gears being shown in Fig. 1 of the drawings. 20 The printing couple is driven from any desired source of power which is applied to the cylinder 20, all of the mechanisms of the machine being driven from the gears carried by the cylinders 20 and 23, a practice 25 which is common in this art.
- Grouped about the planographic cylinder 20 are a plurality of plate cylinders 25, 26, 27 and 28 each adapted to carry a cameo printing plate. The plate cylinders 25 to 30 28 are so mounted as to be capable of movement toward and from the cylinder 20, the impression cylinder 23 also being capable of a similar movement with relation to said cylinder 20.
- 35 The plates upon the cylinders 25 to 28 respectively bear different portions of a complete design so that a planographic surface passing all of said cylinders will be successively inked until the completed design has 40 been collected thereon preparatory to the making of the impression at the cylinder 23.
- As will more fully appear hereinafter, the machine may be so set as to permit the use of any or all of the cylinders 25 to 28 in 45 applying the inked design to either or both of the blankets 21 and 22, or so that some of the plates upon said cylinder will apply the inked design to one of said blankets while others apply it to the other of said blankets 50 as in perfecting work, or in the event that it be desired to cause succeeding impressions to differ from each other.
- While the cylinders 25 to 28 are driven from the cylinder 20 by means of intermeshing gears, the movement of said cylinders toward and from the axis of the cylinder 20 is insufficient to interfere with the proper meshing of such gears. In fact this movement is limited to but a few thousandths 55 of an inch, no substantial pressure being required to effect the proper inking of the cylinder 20 and in fact being undesirable.
- Each of the cylinders 23, 25, 26, 27 and 60 28 has its arbors mounted in a bearing housing slidably radially of the cylinder 20 in
- suitable ways in the frame of the machine, said housings being acted upon by suitable springs having a normal tendency to force the cylinder carried thereby, away from the cylinder 20. The housing for the cylinder 70 23 is indicated at 29 and the springs acting thereon at 30; the housing for the cylinder 25 is indicated at 31 and the springs acting thereon at 32; the housing for the cylinder 26 is indicated at 33 and the springs acting thereon at 34; the housing for the cylinder 75 27 is indicated at 35 and the springs acting thereon at 36; and the housing for the cylinder 28 is indicated at 37 and the springs acting thereon at 38, particular reference 80 being had to Fig. 5 of the drawings, it being understood that this mechanism is duplicated upon opposite sides of the machine.
- Mounted adjacent the housings 29, 31, 33, 85 35 and 37 respectively are eccentric shafts 39, 40, 41, 42 and 43 adapted to operatively engage said housings and force them toward the cylinder 20 against the tension of the springs 30, 32, 34, 36 and 38, when said shafts are turned in one direction, and permit said springs to move said housings and their contained cylinders away from said cylinder 20 when the shafts are turned in the other direction.
- Co-operating with each of the eccentric 90 95 shafts is an actuating mechanism through which power derived from the source of power actuating the machine, may be utilized for causing engagement of the members of the printing couple and of the plates upon the various plate cylinders, with the blankets upon the planographic cylinder 20, this power while derived from the one source being applied to each of said shafts and their actuating mechanisms through entirely 100 independent mechanisms including setting devices, each of which may be so adjusted 105 as to be entirely inoperative to actuate said mechanisms to disengage the cylinders 23, 25, 26, 27 and 28 from the cylinder 20 while the machine is running, or to cause an intermittent engagement and disengagement of said cylinders.
- Each of said setting devices associated 110 115 with the plate cylinders is so constructed as to permit it to be so set by a manual control mechanism as to cause it to engage the actuating mechanism associated therewith to rotate the eccentric shaft in a direction to permit movement of its cylinder away from the planographic cylinder, but prevent its engagement with said mechanism in a manner to cause a return movement of said cylinder into engagement with said planographic cylinder. In conjunction with this setting 120 125 means, I provide means whereby any setting mechanism may be so locked as to maintain its cylinder in inoperative relation to the planographic cylinder.
- Since the continuously operating, power 130

applying devices associated with each of the plate cylinders is identical with every other, a detail description of but one of these mechanisms will be entered into, corresponding parts of the other devices being specifically referred to by different reference numerals.

Referring to the eccentric shaft 40 operative upon the housing 31, the actuating mean therefor comprises a crank arm 44 carried by said shaft and connected with the long arm of a bell crank lever 45 by means of the link 46. The short arm of the bell crank lever 45 carries a stud 47 preferably carrying an anti-friction roll adapted to be engaged by the setting device through which power is applied to said bell crank lever.

Mounted adjacent the cylinder 20 and geared to the shaft of this cylinder so as to have its number of R. P. M. correspond with that of said cylinder, is a housed cam 48 having a substantially 180° rise and a corresponding fall. The cam 48 acts upon one arm of a rocking lever 49 which has pivotally mounted on the other arm thereof, a setting plate 50 having an elongated opening therein forming a hook 51 adapted to engage the stud 47 while permitting movement of the plate with relation thereto. The plate 50 also carries an arcuate impact plate 52 which preferably is adjustable, so that its end may be projected across the slotted opening in the plate 50 to cause an actuation of the lever 45 with each actuation of the lever 49 or be so positioned as not to obstruct the slotted opening in said plate, and thus cause the actuation of said lever 45 only when said plate 52 is elevated to cause it to be operatively engaged with the stud 47.

When the hook 51 of the plate 50 is in the operative relation to the stud 47, the eccentric shaft 40 will be actuated to force the housing 31 toward the cylinder 20 and when the impact plate 52 is in the operative relation to said stud, said shaft will be turned in the opposite direction so as to permit the movement of said housing away from said cylinder. When both said hook and said plate are always in the operative relation to said stud, said shaft will be turned in the opposite direction so as to permit the movement of said housing away from said cylinder. When both said hook and said plate are always in the operative relation to said stud, said housing and the cylinder 25 carried thereby will be positioned away from the cylinder 20 during approximately 180° of the movement in arc of said cylinder 20, and will be so positioned during the remaining 180° of such movement as to bring the plate upon said cylinder 25 into engagement with the blanket upon said cylinder, or if a continuous blanket be used, to engage not more than 180° of said blanket. When the plate 52 is so set as not to project within the slotted opening in the plate 50, it is apparent that after the printing plate upon the cylinder 25 has been once brought into the plane of movement of the blanket upon the cylinder 20, it will remain

in this position and the oscillation of the lever 49 will have no operative effect upon the bell crank lever 45, thus permitting the plate upon the cylinder 25 to remain in its operative inking relation to the cylinder 20. 70

Mounted adjacent the plate 50 is a double crank shaft 53, one crank 54 of which has a stud entering an elongated slot in said plate so that by the oscillation of said crank shaft, said plate may be raised or lowered so as to 75 engage or disengage the hook 51 with or from the stud 47 and determine the operative relation of the impact plate 52 to said stud.

The other arm 55 of said crank shaft is 80 connected with the manually operative control mechanism of the machine.

The shaft 53 also has thereon a stop shoulder 56 adapted to be engaged by a swinging dog 57 mounted on the frame of the 85 machine, which dog when brought into the operative relation to said stop shoulder will hold the plate 50 in an elevated position with the hook 51 above the stud 47 and thus prevent power being applied through said stud 90 47 for bringing the cylinder 25 into the inking relation with the planographic cylinder 20.

The setting device co-operating with the eccentric shaft 41 operative upon the housing 33 comprises a crank arm 58 corresponding with the arm 44, a bell crank lever 59 corresponding with the lever 45 and a connecting link 60 corresponding with the link 46. The bell crank lever 59 carries a stud 61 100 corresponding with the stud 47. The setting device is controlled by a housed cam 62 corresponding with the cam 48 which acts upon a rocking lever 63 corresponding with the lever 49 and acting upon a setting plate 105 64 corresponding with the plate 50 and having a hook 65 corresponding with the hook 51 and an impact plate 66 corresponding with the plate 52. A double crank shaft 67 corresponding with the shaft 53 and having 110 arms 68 and 69 corresponding with the arms 54 and 55, and a stop shoulder 70 and co-operating dog 71 carried by said crank shaft corresponding with the stop shoulder 56 and dog 57, are utilized for setting said plate 50. 115

The setting device co-operating with the eccentric shaft 42 operative upon the housing 35 comprises a crank arm 72 corresponding with the arm 44, a bell crank lever 73 corresponding with the lever 45 and a connecting link 75 corresponding with the link 46. The bell crank lever 73 carries a stud 74 corresponding with the stud 47. The setting device is controlled by a housed cam 76 corresponding with the cam 48 which acts upon 120 a rocking lever 77 corresponding with the lever 49 and acting upon a setting plate 78 corresponding with the plate 50 and having a hook 79 corresponding with the hook 51 and an impact plate 80 corresponding with 125 130

the plate 52. A double crank shaft 81 corresponding with the shaft 53 and having arms 82 and 83 corresponding with the arms 54 and 55, and a stop shoulder 84 and co-operating dog 85 carried by said crank shaft corresponding with the stop shoulder 56 and dog 57, are utilized for setting said plate 50. The setting device co-operating with the eccentric shaft 43 operative upon the housing 37 comprises a crank arm 86 corresponding with the arm 44, a bell crank lever 87 corresponding with the lever 45 and a connecting link 88 corresponding with the link 46. The bell crank lever 87 carries a stud 89 corresponding with the stud 47. The setting device is controlled by a housed cam 90 corresponding with the cam 48 which acts upon a rocking lever 91 corresponding with the lever 49 and acting upon a setting plate 92 corresponding with the plate 50 and having a hook 93 corresponding with the hook 51 and an impact plate 94 corresponding with the plate 52. A double crank shaft 95 corresponding with the shaft 53 and having arms 96 and 97 corresponding with the arms 54 and 55, and a stop shoulder 98 and co-operating dog 99 carried by said crank shaft corresponding with the stop shoulder 56 and dog 57, are utilized for setting said plate 50.

The throw-off mechanism for the impression cylinder 23 comprises an oscillatory plate 100 having pivotally connected thereto a link 101 which is connected with a crank arm upon the eccentric shaft 39. This plate is pivoted at 102 and has mounted upon opposite sides of said pivotal point, studs 103 and 104 bridged by a plate 105 spaced away from the said plate to permit the passage of the thrust member 106 having the shoulders 107 and 108 adapted to engage said studs respectively. One end of said thrust member is connected to one arm of the bell crank lever 109, the other arm of which lever co-operates with a cam 110 carried by the cylinder 20 and rotating therewith. Said cam has two diametrically opposite rises 111 and 112 thereon so as to impart two oscillations to the lever 109 with each rotation of said cylinder 20.

Since under some conditions it is desirable to move the impression cylinder 23 away from the cylinder 20 independently of any movement of the plate cylinder, I provide two independently operative means acting upon the thrust member 106, manually controlled from adjacent the feed shelf, one of said means being adapted to be actuated simultaneously with the setting plates of the various plate cylinders and the other being adapted to be actuated entirely independently thereof.

Associated with the impression cylinder 23 is a plate cylinder 113, the arbors of which are suitably mounted in housings 114

slidable radially of said impression cylinder, being normally forced away from said cylinder by the springs 115. Acting upon the housing 114 is an eccentric shaft 116 having a crank arm 117 connected with the plate 100 by the link 118 so as to force said plate cylinder into engagement with the impression cylinder substantially simultaneously with the engagement of said impression cylinder with the planographic cylinder 20 and permit said springs to move said plate cylinder away from said cylinder 23 simultaneously with, but to a slightly greater extent than, the movement thereof away from said planographic cylinder.

Since the cylinder 113 is of the same diameter as, and is driven from, the impression cylinder 23 so as to limit its operative effect to the blanket upon said impression cylinder, the throw-off mechanism is positive, no means being required to permit adjustment of the plate to cause intermittent movement of the plate cylinder with relation to the cylinder 23.

Pivottally mounted in any position convenient to the feed shelf as upon the arbor of the cam 90, is a spider 119 having five radiating arms, the lengths of which vary according to the effective leverage of the crank arms with which they are respectively connected. Pivottally connected with one of said arms is a link 120 which is also slidably connected by means of a swivel with the crank arm 55. Springs 121 and 122 encircle and bear against shoulders carried by said link and upon opposite sides of said swivel, a construction which permits movement of said spider independently of that of the crank shaft 53 in either direction, thus permitting movement of the plate 50 when it is disengaged from the stud 47, when the plate 52 is so set as to cause the plate cylinder to be constantly in the engaging relation to the planographic cylinder 20, or when no pressure is being applied to said stud when the plate 52 is otherwise set.

The link 123 is connected with the crank arm 69 and to another arm of said spider by means of the springs 124 and 125 having the same operative effect as that above referred to with relation to the setting means for the throw-off mechanism associated with the cylinder 26.

Another arm of said spider is connected by the link 126 and springs 127 and 128 with the crank arm 83 associated with the throw-off mechanism for the cylinder 27.

Another arm of said spider is connected by the link 129 and springs 130 and 131 with the crank 97 for actuating the setting mechanism for the throw-off mechanism for the cylinder 28.

The remaining arm of said spider is connected by means of the link 132 with the bell crank lever 133 carrying a swivel in

which a link 134 has a sliding fit, one end of said link 134 being connected to the thrust member 106 and the other end of said link being connected with said bell crank lever 133 by means of the springs 135 and 136 acting between the swivel of the bell crank lever 133 and abutments upon said link 134.

Connected with one of the arms of the spider 119 is a connecting rod 137, one end of which is pivoted to said arm and the other end of which is pivoted to the arm of a crank shaft 138 adapted to be manually actuated by means of the handle 139 or by means of a rack and pinion mechanism 140, said rack being carried by the connecting rod 141 pivotally connected with a rocking lever 142 below the foot board adjacent the feed shelf, the opposite arms of said lever 142 carrying foot plungers 143 and 144 so that the crank shaft 138 may either be actuated by hand or by stepping on one of said plungers.

Also mounted adjacent the feed shelf is a crank shaft 145 the arm of which is connected by means of the link 146 with the crank arm 147 to which is also connected a link 148 pivotally connected with the thrust member 106 so that this member may be actuated entirely independently of the spider 119, if so desired.

By using the oppositely disposed springs operative upon the double crank shaft through which the setting plates corresponding with the plate 50 are actuated, the throw-off mechanism may be set at any time, but will become operative only upon the completion of the cycle of operation of the machine and during which the mechanism is so set.

Associated with each of the plate cylinders is an inking mechanism, the mechanism associated with the cylinder 25 being indicated by A, that associated with the cylinder 26 by B, that associated with the cylinder 27 by C, that associated with the cylinder 28 by D and that associated with the cylinder 113 by E. The general construction and arrangement of each of these mechanisms and its mode of operation is identical with every other, with the exception that the mechanisms B and C have associated therewith three ink founts while the remaining mechanisms have only two, a variation of construction which requires no modification of the mechanism other than the addition of one ductor or doctor roll and its associated cutting and distributing roll.

In view of the complicated nature of the mechanism, but one of these mechanisms will be described, corresponding reference numerals being applied to corresponding portions of other mechanisms where necessary to identify the relation of parts, and specific reference being had to the additional

parts required by the use of the third fount in the mechanisms B and C.

Referring more particularly to Figs. 3, 5, 12 to 16 and 20, each inking mechanism includes therein a plurality of ink founts of the usual construction having an intermittently actuated roll from which the ink is conveyed to the ductor or doctor rolls. Two of these founts 149 and 150 are associated with each of the inking mechanisms, B and C having an additional fount 151.

The rolls associated with the founts 149 and 150 are indicated at 152 and 153, there being associated with each roll a swing frame 154 and 155, the latter of which is connected by the pitman 156 with the crank wheel 157. Said frames respectively carry pawls 158 and 159 adapted to cooperate with the ratchet wheel carried by said fount rolls. Crank arms carried by said frames are connected by the link 160 so as to permit their actuation from the same source of power.

The ink fount roll 161 associated with the fount 151 is adapted to be actuated by the walking beam 162 connected by the link 163 with the arm to which the link 160 is connected, and with the swing frame 164 carrying a pawl 165 co-operating with the ratchet wheel upon said roll 161, by means of the link 166. In this manner all of the ink fount rolls are simultaneously actuated from a single source of power.

The various ink founts 149, 150 and 151 are adapted to apply inks of a plurality of different colors through the ink distributing rolls associated therewith, each fount receiving an ink of but one color, the different colored inks being applied to the ink distributing rolls in parallel stripes with their edges in absolute register through a particular construction and arrangement of the ductor rolls of the different founts in each inking mechanism. The width of the stripes of ink and their location upon the distributing rolls in relation to the printing plate, is defined by the ductor rolls. The particular arrangement of ink founts and ductor rolls is shown in Fig. 20.

No vibrating member for cutting the ink upon the distributing and inking rolls as commonly used in the printing art, is used. Ink founts 151 are used to permit a greater range as to the colors used with each plate, although the color scheme may be varied indefinitely according to the number of plate cylinders used in transferring or applying the completely inked design to the planographic offset cylinder 20.

Each fount is provided with the usual manually operative turning mechanism 168 for the ductor roll associated therewith.

In further describing the inking mechanism, reference will be had first to the general arrangement of the distributing and

inking rolls; the means by which some of said rolls will have movement simultaneously with the movement of the plate cylinders with which they are associated, 5 both toward and from the planographic cylinder 20; the means by which the ink applied to these rolls will be blended so as to give a chromatic effect to the imprint through the actual mixing of different colors

10 of the ink while being conveyed from the ductor or doctor rolls to the inking rolls, and while upon the latter, and to the ductor or doctor roll mechanism including the means by which this mechanism may be 15 made inoperative simultaneously with the movement of the plate cylinder away from the planographic cylinder, although it is to be understood that this automatic mechanism is supplemented by a manually operative control so that they may be moved out 20 of operation independently of the actuating means for the plate cylinder, and if desired permit the automatic mechanism being entirely dispensed with.

25 The inking rolls 169 which are of ordinary printer's roll composition, are four in number arranged in pairs, each pair receiving its ink from a metallic distributing roll 170—171 which rolls also form a part of 30 the blending mechanism of the machine, to be more fully referred to hereinafter. At 172 is a metallic inking roll of large diameter forming a part of the ink distributing system, ink being taken from this roll and 35 applied to the rolls 170 and 171 through the medium of the rolls 173 which are of the ordinary printer's roll composition.

At 174 is a second large metallic ink distributing roll disposed between which and 40 the distributing roll 172 are the composition rolls 175 and 176 associated with the rolls 174 and 172 respectively, and an intermediate metallic roll 177 of small diameter bearing upon each of the rolls 175 and 45 176. The ink is applied to the metallic roll 174 by the ductor rolls 178—179 associated with the founts 149—150 respectively.

The roll 178 has associated therewith a 50 nonvibratory cutting roll 180, a similar roll 181 being associated with the ductor roll 179.

Said ductor rolls and the associated ink rolls are both of printer's roll composition, so that with this exception throughout the inking mechanism ink is transferred successively by metallic to composition rolls until it is finally applied to the plate by means of composition rolls. At no point in this mechanism except as noted does a composition roll ever bear against another composition roll, nor a metal roll against another metal roll. By thus alternating the composition and the metal rolls, I secure an effective thin distribution of the ink suitable for tint work and without any mixture

of the ink upon the rolls, unless I desire to 65 employ a blending mechanism.

When the fount 151 is used, this mechanism also includes a metallic distributing roll 182 of large diameter, a printer's composition roll 183 engaging same and the metallic roll 174, and an additional ductor roll 184 having associated therewith a cutting roll 185.

The frame supporting the rolls 169, 170, 171 and 173 carries impact members 186 and 75 187 adapted to engage the frame supporting the plate cylinder so as to permit movement of the inking mechanism away from the plate cylinder during the make-ready of the machine and to impart movement to 80 said frame carrying the inking rolls simultaneously with the movement of said plate cylinder by the throw-out mechanism. Said frame is normally thrust toward said plate cylinder by the spring-pressed rods 188 and 85 189 slidably mounted in the carriage carrying said rolls slidably mounted in the lugs 190 and 191 on the carriage supporting the inking mechanism. Wherever necessary the frame of the machine has elongated openings 90 therein to permit movement of the frame without disturbing the relation of the various fixed rolls as 172 and their gears.

The metallic rolls are all positively driven from a gear train meshing with the gear of 95 the plate cylinder. The composition rolls are all frictionally driven from said metal rolls.

The blending mechanism associated with a machine embodying my invention, is solely 100 for the purpose of mixing different colored inks while they are passing from the ink founts to the plates upon the plate cylinder, and has no function in conditioning the ink upon said cylinders as with ordinary vibrating rolls. In fact this blending mechanism is so constructed that it may be made totally 105 inoperative when it is desired to use the machine so as to have distinctly contrasting colors appear upon the imprint, it being possible to apply ink to the distributing rolls in parallel strips and avoid any overlapping 110 of these strips while bringing the edges into absolute register or contact one with the other. This blending mechanism is also so 115 constructed that the extent to which the inks are mixed may be varied to secure any desired blending effect of the inks in the imprint and the desired strength in the secondary color effects secured by this blending. 120

The actuating mechanism for the various blending rolls 170, 171 and 177 consists of a walking beam 192 carrying shoes 193 upon opposite ends thereof adapted to enter the 125 grooved pulleys 194 carried by the arbors of the rolls 170 and 171, said arbors being slidably mounted in suitable bushings in

- the frame of the machine. This walking beam is pivoted between suitable brackets 195 and 196 carried by the frame of the machine adjacent the shaft of the roll 172. 5 Carried by said walking beam is a forked arm 197 entering which is the rounded arm 198 of a bell crank lever idly mounted upon the shaft of said roll 172. The other arm of said bell crank lever is shown at 199. 10 Mounted adjacent the roll 172 and driven therefrom through a suitable gear train, is a crank disc 200 having a slotted way 201 therein in which is seated a crank block to which is connected the rod 202, the other 15 end of which is connected with the arm 199 of the bell crank lever operative upon the walking beam 192. Said crank block is adjustable radially of the slotted way 201 being adapted to be set in any desired position by means of a lead screw 203 carried by the crank disc 200. In this manner the crank may be set co-axially with the disc 200 or eccentrically thereof to any desired extent, thus either permitting the bell crank 20 25 lever 198—199 to remain stationary or to be oscillated to any desired extent.
- The arbors of the rolls 170 and 177 are each provided upon the opposite side of the machine to that upon which the lever 192 30 is located, with grooved pulleys 204 and 205 co-operating with which are shoes carried upon opposite ends of the rocking lever 206 pivotally mounted in the frame of the machine at 207 so that movement will 35 be imparted to the roll 177 through the medium of the roll 170. Both arms of the lever 206 are of the same length as well as the two arms of the walking beam 192, so that the axial movement of the rolls 170, 171 40 and 177 will be the same, thus causing succeeding blending actions when the crank pin block with which the connecting rod 202 is connected is set to impart vibratory movement to said rolls.
- 45 The gear train between the arbor of the roll 172 and the arbors of the rolls 170 and 171 includes wide idler gears 208 and 209 (see Fig. 16) mounted upon studs carried by the frame of the machine so as to 50 compensate for the axial movement of said rolls 170 and 171.
- Upon opposite sides of the ink founts 149 and 150 are mounted the oscillatory slotted frames 210 and 211, the slots of 55 which open upwardly and are adapted to receive the arbors of the ductor or doctor rolls 178 and 179 and the cutting rolls 180 and 181 associated therewith respectively. These frames are idly mounted upon the 60 shafts 212 and 213 and are provided with heels 214 and 215 respectively in which are mounted the adjustable set screws 216 and 217. Each of the frames 210—211 is normally thrust toward the ink fount associated 65 therewith by the spring rods 218 and 219. Keyed or otherwise secured to the rock shaft 212 is a bell crank lever, one arm of which 220 is adapted to operatively engage the set screw 216 and carries an anti-friction roll 221 adapted to be engaged by the cam 70 222 carried by and rotatable with the gear driving the distributing roll 174. The other arm 223 of said lever is connected by the link 224 with the arm 225 of a bell crank lever keyed or otherwise secured to the shaft 75 213 and having an arm 226 adapted to operatively engage the set screw 217. In this manner with a two-fount inking unit both ductor or doctor rolls are simultaneously driven from the same source of power and alternately engage the ink fount rolls and the distributing roll 174.
- The set screws 216 and 217 permit the regulation of the throw of the frames 210—211 so as to secure the desired engagement 80 of the ductor or doctor rolls with the ink fount roll and the distributing roll. Carried by each of the frames 210—211 is a projecting tongue 227—228 adapted to engage the swing frames carrying the pawl for rotating the ink fount roll so as to cause the ductor or doctor roll to be held out of engagement with the ink fount roll until the completion of the actuation of said ink fount roll. 85
- It is desirable, in a machine of this type, to provide means whereby the ductor or doctor rolls will be made inoperative as to the distributing rolls substantially simultaneously with the disengagement of the 90 plate or form cylinder with the planographic cylinder so as to prevent too great an accumulation of ink upon the distributing rolls or upon the plates upon the plate cylinder, or to provide means whereby this 95 result may be secured so that when the plate cylinder is thus disengaged from the form cylinder, the operative effect of the inking mechanism may be stopped.
- To this end, I provide means which may 100 be actuated either manually or automatically, adapted to be operatively engaged with the link 224 and hold it in a position where the spring rods 218—219 will be inoperative in relation thereto. This means comprises 105 a swinging cam 229 idly mounted upon a shaft intermediate the shaft 213 and the plate cylinder with which the inking mechanism is associated. This cam has an arm 110 230 extending radially of said shaft which is connected by means of the link 231 with a crank arm 232 carried by the shaft 233 upon which the distributing roll 172 is loosely mounted. This shaft upon the other side of the machine has secured thereto a 115 hand lever 234 by means of which the shaft is rocked manually. This lever 234 carries a crank arm 235 acting upon which is a hooked end of a link 236, the other end 120 of which is connected to a crank arm 237 125 130

carried by the eccentric shaft for imparting movement to the plate cylinder housing. Clearance is provided within the hooked end of said link 236 so as to compensate for the difference in throw of the arm 237 and the cam 229, necessitated by mechanical conditions about the machine. I employ a hook so that if desired the link 236 may be removed from the machine entirely, and thus limit stoppage of the ductor or doctor rolls to solely manual means.

When employing a three-fount unit, the above mechanisms will be the same except that the frame 211 will have an extension 15 238 carrying a slotted frame 239 adapted to receive the arbors of the ductor or doctor roll 184 and its cutting roll 185, the top of one of the arms of said slotted frame being adapted to engage the swing frame 20 164 instead of using a projection such as 227 or 228.

Instead of using the link 231 connecting the arm 230 with the crank 232, the end of said crank 232 may be provided with an elongated slot straddling a stud upon said arm 230. This, however, is merely a matter of design.

The inking mechanism associated with each of the plate cylinders is slidably 30 mounted upon the main frame of the machine adapted to be actuated by means of any desired mechanism actuated by a hand wheel shown at 240 in Figs. 1 and 12, so as to move these inking mechanisms away 35 from the plate cylinders and facilitate the makeready of the machine. Since movement of inking mechanisms in this manner and for this purpose is old in the art, a detail description of the mechanism for accomplishing this movement is unnecessary.

The frame 241 carrying the inking mechanism E is pivotally mounted at 242, the pivot on one side of the machine carrying a worm gear 243 adapted to be engaged by 45 the worm shaft 244 so that when the machine is to be used as a perfecting machine, said inking mechanism may be swung upwardly away from the plate cylinder 113 to facilitate the makeready of this cylinder.

50 The detail construction of the feed shelf mechanism with relation to the feeding of sheets is immaterial to my present invention, as such is made the subject matter of a separate application Serial Number 535,160, filed Feb. 9, 1922, pending concurrently herewith. It is my intention in the present application, however, to include that feature of said feed shelf mechanism, designed for the purpose of facilitating the make-ready of the press. For this purpose the inclined portion of the feed shelf adjacent the impression cylinder 23 and the planographic cylinder 20 is made in two sections 55 245 and 246 pivoted together at 247. The section 245 is pivoted to have movement

about the shaft 248, which carries a segmental worm gear 249 acted upon by the worm shaft 250 carrying an operating hand wheel 251. The underside of the shelf section 246 is provided with a cam 252 bearing 70 against a roller stud 253 so that with the elevation of the section 245, the engagement of said cam 252 with the roller 253 will cause the elevation of the portion of said section adjacent the hinged connection 75 of same with the section 245 to be simultaneously raised causing the shelf to break at the pivotal point and thus be moved away from the cylinder 20. The lowering 80 of the section 245 by the same mechanism will result in a reversal of this action, the cam 252 coming to rest upon suitable supports upon the frame of the machine so as to keep the shelf substantially rigid while 85 in use.

While the raising of the feed shelf in the manner described will permit access to the planographic cylinder 20 and the plate cylinder 28, the clearance is not sufficient to permit that free access to the cylinder 20 90 which is sometimes desirable, to meet which condition I provide the carriage 253^a for said cylinder 28 with travellers co-operating respectively with lead screws 254 upon opposite sides of the machine so that said cylinder in its entirety may be moved away from the cylinder 20 to a sufficient extent to permit free access to said cylinder 20. The lead screws 254 upon opposite sides of the machine are connected by gearing 255 so 100 as to operate in unison.

The cams 48, 62, 76 and 90 are adjustably mounted by means of the screws 256 upon the shafts carrying same so that these cams may be caused to operate similarly upon the various setting plates, or may be turned 180° so as to permit variance in the timing of any of said setting plates to permit the utilization of any desired grouping of the plate cylinders with relation to the blankets upon the planographic offset cylinder 20. By changing the timing of different cams 110 all of the cylinders may be caused to transfer the ink design upon either or both blankets upon said cylinder 20, according to the set of said cams and the setting plates, or some of said cylinders 23 may be caused to ink one of the blankets upon said cylinder 20, and others to ink the other 115 blanket upon said cylinder.

120 The machine of my invention is particularly adapted for printing large sheets of paper having multicolor imprints throughout the entire surface thereof, being particularly adapted for producing a large number of similar designs upon each sheet. Since each design must have the same colors in the same relation, and since different inks have to be handled differently while 125 in the founts to secure the proper feeding 130

thereof, I provide a novel arrangement for the distribution of the ink throughout the distributing and inking rolls, whereby ink of one color may be used in each fount, and 5 yet have only isolated stripes thereof transferred by each ductor roll to the distributing roll 174—182, the aggregate of these stripes however, amounting to a complete inking of said distributing roll from side to 10 side thereof, within the range of the surface of the plates to be inked.

In securing the desired result, I form each ductor roll of a sequence of spaced discs of ordinary printer's roll composition, the discs 15 *a* upon one of the ductor rolls as 178, when two founts are used, being spaced apart a distance identically equal with the width of the discs *b* upon the ductor roll 179 so as to form no line of demarcation between the 20 stripes upon the distributing roll 174, as a result of the staggering of these discs with relation to each other. When three founts are used, the discs *a* forming one of the ductor rolls as 178 will be spaced apart a distance 25 equalling the width of the discs *b* and *c* forming the ductor rolls 179 and 184, the discs upon the different ductor rolls being staggered, or offset, with relation to each other with the same effect as is above referred to.

By this construction, irrespective of the number of ink founts which may be employed, the width of the discs *a*, *b* and *c* upon all of the ductor rolls will be equivalent 30 to one continuous ductor roll, the results secured in effect being a mere division of one ductor roll so as to form thereof a plurality of ductor rolls having parallel, registering, ink-conveying surfaces for applying 35 ink in stripes to the distributing roll 174, either directly when two founts are used, and directly and indirectly when three or more founts are used. By the above construction, no difficulty is secured in adjusting 40 the fount for uniform feeding throughout each ductor roll, it still being possible to secure a wide range of colors by using all of the plate cylinders 25 to 28 and employing 45 a different color in each of the founts associated with said cylinders respectively.

As shown in Fig. 18, each of the plate cylinders is so mounted as to be slidable laterally of the machine, the housing 257 carrying the cylinder having a bridge 258 on 50 which is mounted a high pitch screw 259 bearing upon the end of the arbor of the cylinder so as to facilitate lateral adjustment of the cylinder in its entirety for the purposes of securing lateral register.

60 The operation of the herein described mechanism is substantially as follows:—

The detailed operation of the various mechanisms of the machine will be readily understood from the foregoing description, 65 it being understood that the essential char-

acteristic of the machine is the production of an imprint in a plurality of colors with a single impression, the color arrangement being entirely within the control of the operator and being susceptible of wide variation as a result of the use of inks of different colors in the several founts of each feeding mechanism, and the separation of the completed design into parts having any desired contour, with the use of the different 70 parts on different plate cylinders. The fragmentary portion of continuing lines of the completed design upon different plates permits any desired color grouping upon the 75 completed design irrespective of the color arrangement upon the inking rollers, which of necessity must be in parallel stripes with or without adjoining edges blended. This result is very much simplified, since 80 designs upon different plates may partially or fully overlay those upon other plates, thus permitting a number of different colors to appear throughout the entire width of the 85 imprint, without any stripe effects.

The plates upon the cylinders 25 to 28 each 90 contain a fragmentary portion of a complete design or a plurality of such portions disposed throughout each plate, complementary portions of the complete design being carried by the plates upon different cylinders. These plates are cameo plates, so 95 that ink from the distributing rolls of each inking mechanism while appearing in parallel stripes upon said rolls, will be applied only to the raised lines of a plate, the extent 100 of the application of the ink thus being governed by the plate, but the location of the different colors being governed by the inking rolls. By alternating metallic inking 105 rolls and composition rolls, I secure an effective cutting and uniform distribution of the ink without likelihood of the broadening of the stripes through pressure or suction conditions between the rolls.

By using narrow discs *a*, *b* and *c* upon the 110 ductor rolls, I can secure any desired distribution of the ink of any color throughout the width of the plate and can provide for any desired combination of colors upon each plate, and can carry the same combination 115 of colors in groups for work requiring duplication of a design upon a plate.

By employing a plurality of plate cylinders all operating to apply different portions of a design in ink to the same planographic surface and associating with each plate cylinder, a plurality of founts as above described, the number and disposition of colors employed in a single impression may 120 be widely varied, thus permitting the production of intricate, complicated color designs difficult if not impossible of reproduction in ordinary color presses. The complexity of the color scheme of the imprint 125 may be greatly increased by the blending 130

mechanism of the machine, particularly as this mechanism associated with the inking mechanism of each plate cylinder, is under independent control and may or may not be so set as to have the same degree of blending, or may not be used at all, if so desired.

In addition to the various color effects which may be secured through the skillful distribution of inks from the different founts and the setting of the blending mechanism, the construction of the printing machine herein described is such that any desired number of plate cylinders may be used to transfer the design to either or both surfaces, 21—22, on the planographic cylinder 20. It is also possible to use the impression cylinder 23 as a printing cylinder, so as to do perfecting work, with the designs upon opposite sides of the sheet in absolute register, it being possible to utilize one surface of the cylinder 20 for transferring a portion of the design to the planographic surface of the cylinder 23 so as to cause the design impressed by said cylinder to be entirely lacking in stripe or streamer effect in the colors. It is also possible to use the different planographic surfaces 21 and 22 upon the cylinder 20 for different designs in multi-color, so as to permit the printing of two different designs with each cycle of the press. Under the above conditions the cylinder 23 may be employed to produce perfecting work in which the sheets bearing these different designs may have the same design impressed thereon in exact register with the designs impressed thereon by the cylinder 20.

The machine as shown in the drawings, is so set as to secure the above result and will first be described with relation to this setting of the machine, the result secured by different settings thereof being thereafter referred to.

Referring particularly to Fig. 5 of the drawings, when the cams 48, 62, 76 and 90 are set as shown, the plates upon the cylinders 25 and 26 will engage only one of the blankets, as 21, while the plates upon the cylinders 27 and 28 will engage only the planographic surface 22 upon said cylinder 20, thus simultaneously inking both of said planographic surfaces by means, however, of different plates and their associated inking mechanism.

Since the cylinder 23 has two revolutions to each revolution of the cylinder 20, it is apparent that the planographic surface 24 upon said cylinder 23 will co-operate with each of the planographic surfaces 21 and 22, being inked with each revolution thereof by means of the plate cylinder 113 and the inking mechanism E.

Since each of the cams 48, 62, 76 and 90 have the same R. P. M. as the cylinder 20, and since the rise of each of said cams ex-

tends about 180° of the cam, it is apparent that the engagement of the plate cylinders 25 to 28 with the respective planographic surfaces upon the cylinder 20, will continue during only one-half of the revolution of each cylinder 20, and that the mechanisms actuated by said cam, which will be more fully described in connection with one of said mechanisms only, will, upon the completion of 180° of movement in arc of said cylinder 20, move all of said plate cylinders away from the planographic cylinder 20 during the next 180° in arc of movement of said cylinder. Hence while the planographic surface 21, after it has been inked by the plate cylinders 25 and 26 is passing the cylinders 27 and 28, the plates upon said cylinders will be out of engaging relation to said surface, the plates upon the cylinders 25 and 26 in the meanwhile being similarly out of engaging relation to the planographic surface 22.

If it be desired to use but one of the blankets 21 or 22, two of the cams, 48 and 62 or 76 and 90, may be reset, with a movement of 180°. When said cams are so set, the cylinders actuated thereby will operate dissimilarly. Assuming that the cams to be thus reset are 76 and 90, and that the planographic surface 21 is to be used, it will be apparent that when the plates upon the cylinders 25 and 26 are engaged with said surface 21, the plates upon the cylinders 27 and 28 will be moved away from the cylinder 20 so as not to ink the surface 22. When, upon the completion of the 180° of movement of the cylinder 20, the surface 21 is brought into the operative relation to the plates upon the cylinders 27 and 28, these cylinders will be automatically brought into engagement with said planographic surface, and the cylinders 25 and 26 will be simultaneously moved out of the operative relation to the cylinder 20 so as to apply no ink to the surface 22.

The foregoing adjustment permits the use of either surface 21—22 with all four plate cylinders, or with but two of said cylinders. The former adjustment is desirable when a design is to be transferred from one of said planographic surfaces as 22 to the impression cylinder 23, as a duplication of the design upon both sides of the printed sheet is thus avoided. If it be desired to use the plates upon all four cylinders 25 to 28, upon each of the surfaces 21 and 22, the adjustment for this purpose is secured by means of the setting plates 50, 64, 78 and 92 and the impact plates 52, 66, 80 and 94 carried thereby, said last named parts, with the setting of the machine as heretofore described, being operative upon the studs 47, 61, 75 and 89, with each rotation of said cam, but when all four plate cylinders are to be used for inking, being operative

thereon only when the throw-off mechanism is actuated.

While in the manner above described, I can control the operative relation of the 5 plate cylinders 25 to 28 to the surfaces 21 and 22 upon the planographic cylinder 20, the variations obtainable are susceptible to still greater latitude by reason of the fact that the setting mechanism may be used to 10 make any cylinder inoperative with relation to the planographic cylinder 20 in a manner which will more fully appear hereinafter.

With each rotation of the cams 48, 62, 76 and 90, the rocking levers 49, 63, 77 and 91 15 will be oscillated, carrying with them the setting plates 50, 64, 78 and 92, the rises of said cams respectively moving said plates so as to engage the impact plates 52, 66, 80 and 94 with the studs 47, 61, 75 and 89 and actuate 20 the bell crank levers 45, 59, 73 and 87 in a manner to actuate the cams 40, 41, 42 and 43 to permit the respective plate cylinders to move away from the planographic cylinder 20, irrespective of the setting of the cams. 25 The reverse movement of said levers will engage the hooks, 51, 65, 79 and 93 with said studs and by a reversal of the movement of the cams 40 to 43 force the plate cylinders towards the cylinder 20. 30 By setting the impact plates 52, 66, 80 and 94 so as to project across the slots in said setting plates, said cams 48, 62, 76 and 90 will always have the operative effect of permitting the plate cylinders to move away 35 from the planographic cylinder.

When said impact plates are set as described and as shown in the drawings, each plate cylinder, with each rotation of the cylinder 20, will remain out of engagement 40 with said cylinder during 180° of movement in arc thereof and will engage said cylinder during the other 180° of such movement, which condition is also entirely irrespective of the setting of the cams 48, 62, 76 and 90, 45 which latter will merely govern the timing of this movement so as to control the operative relation of the plates upon the cylinders 25 to 28 to the planographic surfaces 21 and 22 upon the cylinder 20.

50 When it is desired to use all four cylinders upon each of said surfaces 21 and 22, the impact plates 52, 66, 80 and 94 are adjusted upon the setting plates carrying same, so as to not extend across said slot, whereupon the 55 fall of the cams will have no operative effect upon said cylinders 25 to 28 so long as the press is operating. They will, nevertheless, be in a position where the throw-off lever may be actuated so as to cause them to be 60 brought into a relation where they will move all the cylinders 25 to 28 away from the cylinder 20, and the hooks 51, 65, 79 and 93 be brought out of the operative relation to the studs 47, 61, 75 and 89 and thus be incapable 65 of imparting a return movement to said cyl-

inders 25 to 28. Hence, while the setting plates and their appurtenances may be used as a part of the throw-off mechanism, they are also capable of use for controlling the operative effect of the plates upon the cylinders 70 25 to 28 with relation to the printing surfaces upon the cylinder 20, thus modifying the operative effect upon said cylinders of the cams 48, 62, 76 and 90.

If it be desired to stop the machine at any 75 time, the handle 139 or the foot pedal 144 may be used to impart rotary movement to the spider 119, the sole resistance to this movement being the various springs 121, 124, 127, 130 and 136 operative upon the 80 links 120, 123, 126, 129 and 134 pivoted to and extending from said spider to the mechanisms actuating the various setting plates and the thrust member 106. The movement of said links causes the tensioning of the 85 springs operative thereon and will place a stress upon the bell crank levers 55, 69, 73 and 97 and rod 134, so that when the next actuation of the cam 110 positions the thrust member 106 with relation to the studs 90 103—104, so as to permit an upward movement of said thrust member, said levers will impart such a movement to the setting plates 50, 64, 78 and 92 as will disengage the hooks 51, 65, 79 and 93 from their co-operating 95 studs 47, 61, 75 and 89 so that upon a return movement of the rocking levers 49, 63, 77 and 91, the eccentrics 40, 41, 42 and 43 will not be actuated, thus permitting all of the cylinders 25 to 28 to remain out of the operative 100 relation to the cylinder 20.

When the parts are in this position, which may be maintained for any desired term, the dogs 57, 71, 85 and 99 may be engaged with the shoulders 56, 70, 84 and 98 so as to hold 105 any setting plate with its hook out of engagement with the stud co-operating therewith and thus permit all or any of the plate cylinders to be maintained with the plates thereon out of the operative relation to the 110 printing surfaces upon the cylinder 20 to make some plate cylinder inoperative to ink the surface or surfaces upon the cylinder 20, or to facilitate the makeready or the cleaning of the press.

Substantially with the disengagement of the plate cylinders through springs acting thereon under the control of the cams 48, 62, 76 and 90, from the cylinder 20, the impression cylinder 23 will be moved away from 120 said cylinder 20 as a result of the oscillations of the plate 100, under the control of the thrust member 106, the movement of said plate 100 through the link 118 and the eccentric 116 permitting movement of the plate 125 cylinder 113 away from the cylinder 23.

By movement of the handle 139 in the opposite direction, or by actuating the pedal 143, the reverse of the operations above referred to is secured. By this construction 130

the power for the press may be applied to the various plate cylinders and the impression cylinder to effect an instantaneous shifting of these cylinders immediately following, or immediately preceding an impression interval, without any material effort on the part of the feeder.

If it be desired to impart movement to the impression cylinder 23 independently of the spider 119, and without disturbing the relation of the various plate cylinders, this may be done through the medium of the hand lever 145 and link and lever mechanism 147 and 148 acting directly on the thrust member 108.

With the movement of each of the plate cylinders and the impression cylinder away from the planographic cylinder 20, the inking mechanism associated with said plate cylinders will have movement therewith, the inking rolls remaining in inking relation to the plates upon said cylinders.

If, however, it be desired to stop the application of ink from the founts to the distributing rolls, this may be done either manually or automatically as to the inking mechanisms associated with the rolls 25 to 28. This is done manually by means of the hand lever 234, the rocking of which toward the cylinder 20 will oscillate the cam 229 and interpose it in the path of the link 224 so as to prevent a return movement of the supports for the ductor rolls under the spring rods 218-219, thus preventing the application of ink to each distributing roll 174, and effectively preventing the accumulation of ink upon the distributing and inking rolls.

The application of ink to the distributing rolls by the ductor rolls may also be stopped with each movement of the plate cylinders 25 to 28 away from the cylinder 20 by engaging the hooked end of the link 236 with the crank arm 235, thus causing movement of the crank controlling the cam for causing movement of the plate cylinder toward or from the planographic cylinder, to impart the desired rocking movement to the hand lever with the same effect as is above described, an elongated opening being provided in said hook so as to permit the ductor roll to be made inoperative irrespective of the movement of the plate cylinders.

The holding of the ductor rolls in a position where they are not permitted to engage the distributing roll 174 is possible since while the cam 222 operates continuously upon the rock arm 220, the screws 216-217 carried by the ductor roll frames respectively and actuated through the medium of said rock arm, will permit said frames to be arrested in any position between the distributing roll 174 and the ink fount roll, so that they may be held out of engagement with the latter irrespective of the continued

function of said cam 222, the purpose being not to prevent the engagement of the ductor rolls with said roll 174 but to prevent the continued application of ink thereto as a result of the alternate engagement of the ductor rolls with the ink fount rolls and with said roll 174.

While the operation of the blending mechanism will be apparent from the detailed description of each of these mechanisms, attention is called to the fact that since each blending mechanism is actuated from an individual source of power, and may be adjusted entirely independently of the other blending mechanisms, the inks applied to different plates may be blended or not, as desired, adjacent the adjoining edges of the stripes of ink upon the distributing and inking rolls, and the extent of such blending may be varied in different inking mechanisms.

If it is not desired to blend the ink, the crank connection between the link 202 and the crank wheel 200, may be brought with its axis concentric with that of said crank wheel, radial adjustment of said cranks to different extents causing different degrees of lateral reciprocation of the blending rolls so as to get any desired chromatic effects. Ordinarily the blending of colors is practiced as imprints containing such blended colors do not only secure a pleasing effect but make reproductions by ordinary printing mechanisms extremely difficult, particularly as the inks employed may be either primary or secondary colors.

It is not my intention to limit the invention to the precise details of construction shown in the accompanying drawings, it being apparent that such may be varied without departing from the spirit and scope of the invention.

Having described the invention, what I claim as new and desire to have protected by Letters Patent, is:

1. A printing machine embodying therein a collecting cylinder having a plurality of offset printing surfaces thereon, an impression cylinder, a plurality of plate cylinders each of a diameter to have two revolutions to each revolution of said collecting cylinder, and each having a cameo printing plate thereon, means operative upon said plate cylinders to alternately move the plates thereon into and out of engaging relation to said printing surfaces, means actuated by said collecting cylinder, operative connections between said last named means and the means operative upon a plate cylinder, means whereby said connections may be made operative or inoperative with relation to said first named means to cause the plates upon said plate cylinder to engage only one of the printing surfaces upon said collecting cylinder, or maintain said

- plates in engaging relation to said surfaces, whereby said plates may be employed to apply an inked design to either or both surfaces upon said collecting cylinder, and an inking mechanism associated with each of said plate cylinders. 5
2. A printing machine embodying therein a collecting cylinder having a plurality of offset printing surfaces thereon, an impression cylinder, a plurality of plate cylinders each of a diameter to have two revolutions to each revolution of said collecting cylinder, and each having a cameo printing plate thereon, means operative upon each of 10 said plate cylinders whereby it may be moved toward or from said collecting cylinder, a plurality of members, one for each plate cylinder, means whereby said members are driven from said collecting cylinder, operative connections between each of said members and the means operative upon each plate cylinder, means permitting adjustment of said members, whereby the movement of said plate cylinders may be 15 individually controlled to engage the plates thereon with either or both of the planographic surfaces during each revolution thereof, and an inking mechanism associated with each of said plate cylinders. 20
3. A printing machine embodying therein a collecting cylinder having a plurality of offset printing surfaces thereon, an impression cylinder, a plurality of plate cylinders each of a diameter to have two revolutions to each revolution of said collecting cylinder, and each having a cameo printing plate thereon, means operative upon each of 25 said plate cylinders whereby it may be moved toward or from said collecting cylinder, a cam associated with each of said plate cylinders, means actuated by said cam and operative upon said means operative upon said cylinders, whereby said cams are normally operative to move said plate cylinders towards, but are inoperative to move them away from, said collecting cylinder, whereby all of said plate cylinders are utilized to apply an inked design to both of 30 said planographic surfaces, means whereby some of said cams may be so set as to be successively operative with relation to the others, whereby all of said plate cylinders may be made operative as to one of said printing surfaces only, and an inking mechanism associated with each of said plate cylinders. 35
4. A printing machine embodying therein a collecting cylinder having a plurality of offset printing surfaces thereon, an impression cylinder, a plurality of plate cylinders each of a diameter to have two revolutions to each revolution of said collecting cylinder, and each having a cameo printing plate thereon, means operative upon each of 40 said plate cylinders whereby it may be moved toward or from said collecting cylinder, a cam associated with each of said plate cylinders, means actuated by said cam and operative upon said means operative upon said cylinders, whereby said cams are normally operative to move said plate cylinders towards, but are inoperative to move them away from, said collecting cylinder, whereby all of said plate cylinders are utilized to apply an inked design to both of 45 said planographic surfaces, and an inking mechanism associated with each of said plate cylinders. 50
5. A printing machine embodying therein a collecting cylinder having a plurality of offset printing surfaces thereon, an impression cylinder, a plurality of plate cylinders each of a diameter to have two revolutions to each revolution of said collecting cylinder, and each having a cameo printing plate thereon, means operative upon each of 55 said plate cylinders whereby with each rotation of said cams said plate cylinders will be simultaneously moved away from or toward said planographic cylinder, whereby the plates upon some of said plate cylinders will be operative to apply ink to one of said planographic surfaces, and others of said plates upon said plate cylinders will be operative to apply ink to the other of said surfaces, and an inking mechanism associated with 60 each of said plate cylinders. 75
6. A printing machine embodying therein a collecting cylinder having a plurality of offset printing surfaces thereon, an impression cylinder, a plurality of plate cylinders each of a diameter to have two revolutions to each revolution of said collecting cylinder, and each having a cameo printing plate thereon, means operative upon said plate cylinders to alternately move the plates thereon into and out of engaging relation to said printing surfaces, a plurality of members, one for each plate cylinder, means whereby said members are driven from said collecting cylinder, operative connections between each of said last named members and the means operative upon each plate cylinder, means permitting adjustment of said members whereby the movement of said plate cylinders may be independently controlled to engage the plates thereon with either or both of the planographic surfaces during each revolution thereof. means whereby said connections may be made operative or inoperative with relation to said first named means, means whereby any of said connections may be maintained in its inoperative relation independently of the con- 130

- nections operative upon other cylinders, whereby said first named means operative upon any cylinder may be made inoperative to impart movement thereof toward said 5 collecting cylinder, and any desired number of said cylinders may be used to apply an inked design to said collecting cylinder, and an inking mechanism associated with each of said plate cylinders.
- 10 7. A printing machine embodying therein a collecting cylinder having a plurality of offset printing surfaces thereon, an impression cylinder, a plurality of plate cylinders each of a diameter to have two revolutions 15 to each revolution of said collecting cylinder, and each having a cameo printing plate thereon, means operative upon each of said plate cylinders whereby it may be moved toward or from said collecting cylinder, studs, operative connections between said studs and said means, a cam associated with each of said plate cylinders, a rocking lever acted upon by each of said cams, a setting plate carried by each of said levers, 20 a hook and an impact member carried by each of said plates and adapted respectively to co-operate with said studs, whereby with each rotation of said cams, said impact plates will act upon said studs to impart movement to said cylinders away from said collecting cylinder, and said hooks acting upon said studs will impart movement to said cylinders toward said collecting cylinder to cause the plates upon some of said 25 cylinders to apply ink to one of said planographic surfaces and the plates upon the other of said cylinders to apply ink to the other of said surfaces, and an inking mechanism associated with each of said plate cylinders.
- 30 8. A printing machine embodying therein a collecting cylinder having a plurality of offset printing surfaces thereon, an impression cylinder, a plurality of plate cylinders each of a diameter to have two revolutions 35 to each revolution of said collecting cylinder, and each having a cameo printing plate thereon, means operative upon each of said plate cylinders whereby it may be moved toward or from said collecting cylinder, studs, operative connections between said studs and said means, a cam associated with each of said plate cylinders, a rocking lever 40 acted upon by each of said cams, a setting plate carried by each of said levers, a hook and an impact member carried by each of said plates and adapted respectively to co-operate with said studs, whereby with each 45 rotation of said cams, said impact plates will act upon said studs to impart movement to said cylinders away from said collecting cylinder, and said hooks acting upon said studs will impart movement to said 50 cylinders toward said collecting cylinder to cause the plates upon some of said cylinders to apply ink to one of said planographic surfaces and the plates upon the other of said cylinders to apply ink to the other of said surfaces, means whereby the hook upon any of said setting plates may be maintained out of the operative relation to the stud co-operating therewith to prevent movement of the cylinder controlled by said setting plate 55 toward said collecting cylinder, and permit any desired number of such cylinders to be used to apply ink to said collecting cylinder, and an inking mechanism associated with each of said plate cylinders.
- 60 9. A printing machine embodying therein a collecting cylinder having a plurality of offset printing surfaces thereon, an impression cylinder, a plurality of plate cylinders each of a diameter to have two revolutions 65 to each revolution of said collecting cylinder, and each having a cameo printing plate thereon, means operative upon each of said plate cylinders whereby it may be moved toward or from said collecting cylinder, studs, operative connections between said 70 studs and said means, a cam associated with each of said plate cylinders, a rocking lever 75 acted upon by each of said cams, a setting plate carried by each of said levers, a hook and an impact member carried by each of said plates and adapted respectively to co-operate with said studs, whereby with each 80 rotation of said cams, said impact plates will act upon said studs to apply ink to both of the surfaces thereon, and an inking mechanism associated with each of said plate cylinders.
- 85 10. A printing machine embodying therein a collecting cylinder having a plurality of offset printing surfaces thereon, an impression cylinder, a plurality of plate cylinders each of a diameter to have two revolutions 90 to each revolution of said collecting cylinder, and each having a cameo printing plate thereon, means operative upon each of said plate cylinders whereby it may be moved toward or from said collecting cylinder, studs, operative connections between said 95 studs and said means, a cam associated with each of said plate cylinders, a rocking lever 100 acted upon by each of said cams, a setting plate carried by each of said levers, a hook and an impact member carried by each of said plates and adapted respectively to co-operate with said studs, whereby with each 105 rotation of said cams, said impact plates will act upon said studs to apply ink to the other of said surfaces, means whereby the hook upon any of said setting plates may be maintained out of the operative relation to the stud co-operating therewith to prevent movement of the cylinder controlled by said setting plate 110 toward said collecting cylinder, and permit any desired number of such cylinders to be used to apply ink to said collecting cylinder, and an inking mechanism associated with each of said plate cylinders.
- 115 11. A printing machine embodying therein a collecting cylinder having a plurality of offset printing surfaces thereon, an impression cylinder, a plurality of plate cylinders each of a diameter to have two revolutions 120 to each revolution of said collecting cylinder, and each having a cameo printing plate thereon, means operative upon each of said plate cylinders whereby it may be moved toward or from said collecting cylinder, studs, operative connections between said 125 studs and said means, a cam associated with each of said plate cylinders, a rocking lever acted upon by each of said cams, a setting plate carried by each of said levers, a hook and an impact member carried by each of said plates and adapted respectively to co-operate with said studs, whereby with each 130 rotation of said cams, said impact plates will act upon said studs to apply ink to both of the surfaces thereon, and an inking mechanism associated with each of said plate cylinders.

- hook and an impact member carried by each of said plates and adapted respectively to co-operate with said studs, whereby with each rotation of said cams, said impact plates 5 will act upon said studs to impart movement to said cylinders away from said collecting cylinder, and said hooks acting upon said studs will impart movement to said cylinders toward said collecting cylinder to cause the plates upon some of said cylinders to apply ink to one of said planographic surfaces and the plates upon the other of said cylinders to apply ink to the other of said surfaces, means whereby said 10 impact plates respectively may be so set as to be normally inoperative with relation to said studs, whereby said plate cylinders will all be maintained in the operative relation to said collecting cylinder so as to apply ink 15 to both of the surfaces thereon, means whereby the hook upon any of said setting plates may be maintained out of the operative relation to the stud co-operating therewith to prevent movement of the cylinder controlled 20 by said setting plate toward said collecting cylinder, and permit any desired number of such cylinders to be used to apply ink to said collecting cylinder, and an inking mechanism associated with each of said plate cylinders. 25
11. A printing machine embodying therein a collecting cylinder having a plurality of offset printing surfaces thereon, an impression cylinder, a plurality of plate cylinders each of a diameter to have two revolutions to each revolution of said collecting cylinder, and each having a cameo printing plate thereon, means operative upon each of said plate cylinders whereby it may be 30 moved toward or from said collecting cylinder, studs, operative connections between said studs and said means, a cam associated with each of said plate cylinders, a rocking lever acted upon by each of said 35 cams, a setting plate carried by each of said levers, a hook and an impact member carried by each of said plates and adapted respectively to co-operate with said studs, whereby with each rotation of said cams, 40 said impact plates will act upon said studs to impart movement to said cylinders away from said collecting cylinder, and said hooks acting upon said studs will impart movement to said cylinders toward said collecting cylinder to cause the plates upon some of said cylinders to apply ink to one of said planographic surfaces and the plates upon the other of said cylinders to apply ink to the other of said surfaces, means whereby the 45 hook upon any of said setting plates may be maintained out of the operative relation to the stud co-operating therewith to prevent movement of the cylinder controlled by said setting plate toward said collecting 50 cylinder, and permit any desired number of such cylinders to be used to apply ink to one of said planographic surfaces and the other of said cylinders to apply ink to the other of said surfaces, or to cause all of said cylinders to apply ink to one of said surfaces, and an inking mechanism associated with each of said plate cylinders. 55
12. A printing machine embodying therein a collecting cylinder having a plurality of offset printing surfaces thereon, an impression cylinder having an offset printing surface thereon of substantially the same length as each printing surface upon said collecting cylinder, a plurality of plate cylinders each having a cameo printing plate bearing a portion of a complete design thereon adapted to apply an inked design in different colors to the surfaces upon said collecting cylinder, means operative upon said plate cylinders to alternately move the plates thereon into and out of engaging relation to said printing surfaces, a plurality of members, one for each plate cylinder, means whereby said members are driven from said collecting cylinder, operative connections between each of said members and the means operative upon a plate cylinder, means permitting adjustment of said members whereby the movement of said plate cylinders may be individually controlled to engage the plates thereon with either or both of said printing surfaces during each revolution thereof and one of said surfaces upon said collecting cylinder may be employed to transfer an inked design to said impression cylinder while the other of said surfaces will co-operate with said impression cylinder for perfecting printing, and an inking mechanism associated with each of said plate cylinders. 60
13. A printing machine embodying therein a collecting cylinder having a plurality of offset printing surfaces thereon, an impression cylinder having an offset printing surface thereon of substantially the same length as each printing surface upon said collecting cylinder, a plurality of plate cylinders each having a cameo printing plate bearing a portion of a complete design thereon adapted to apply an inked design in different colors to the surfaces upon said collecting cylinder, an inking mechanism associated with each of said plate cylinders, a plate cylinder adapted to apply an inked design to the offset printing surface upon said impression cylinder, an inking mechanism associated therewith, means operative upon said plate cylinders to alternately move the plates thereon into and out of engaging relation to said printing surfaces, a plurality of members, one for each plate cylinder, means whereby said 65

members are driven from said collecting cylinder, operative connections between each of said members and the means operative upon a plate cylinder, and means permitting adjustment of said members whereby the movement of said plate cylinders may be individually controlled to engage the plates thereon with either or both of said printing surfaces during each revolution thereof, and one of said surfaces upon said collecting cylinder may be employed to supplement the action of the plate cylinder associated with said impression cylinder in applying an inked design in a plurality of colors to the offset surface of the impression cylinder, while the other of said surfaces will co-operate with said impression cylinder for perfecting printing.

14. A printing machine embodying there-in a collecting cylinder having a plurality of offset printing surfaces thereon, an impression cylinder having an offset printing surface thereon of substantially the same length as each printing surface upon said collecting cylinder, a plurality of plate cylinders each having a cameo printing plate bearing a portion of a complete design thereon adapted to apply an inked design in different colors to the surfaces upon said collecting cylinder, an inking mechanism associated with each of said plate cylinders, a plate cylinder adapted to apply an inked design to the offset printing surface upon said impression cylinder, an inking mechanism associated therewith, means operative upon said plate cylinders to alternately move the plates thereon into and out of engaging relation to said printing surfaces, a plurality of members, one for each plate cylinder, means whereby said members are driven from said collecting cylinder, operative connections between each of said members and the means operative upon a plate cylinder, means permitting adjustment of said members whereby the movement of said plate cylinders may be individually controlled to engage the plates thereon with either or both of said printing surfaces during each revolution thereof, and one of said surfaces upon said collecting cylinder may be employed to supplement the action of the plate cylinder associated with said impression cylinder in applying an inked design in a plurality of colors to the offset surface of the impression cylinder, while the other of said surfaces will co-operate with said impression cylinder for perfecting printing, and means whereby the operative connections between each of said members and the means operative upon a plate cylinder associated with the collecting cylinder may be made inoperative to cause all of said plate cylinders to remain in their operative relation to both surfaces upon said cylinder.

15. A printing machine embodying there-in a collecting cylinder having an offset printing surface thereon, an impression cylinder associated therewith, a plurality of plate cylinders each having a printing plate bearing a portion of a complete design in relief thereon, and an inking mechanism associated with each of said plate cylinders comprising an ink fount, a continuous ink fount roll associated therewith, a ductor roll co-operating with said ink fount roll and composed of a plurality of spaced discs, inking rolls adapted to apply ink to the plates upon a plate cylinder, and distributing rolls adapted to receive stripes of ink from said ductor roll, work the ink and apply it in stripes to said inking rolls.

16. A printing machine embodying there-in a collecting cylinder having an offset printing surface thereon, an impression cylinder associated therewith, a plurality of plate cylinders each having a printing plate bearing a portion of a complete design in relief thereon, and an inking mechanism associated with each of said plate cylinders comprising a plurality of ink founts adapted to each receive an ink of a different color, a continuous ink fount roll associated with each of said founts, ductor rolls associated with said ink fount rolls respectively each consisting of a plurality of spaced discs, the discs upon one roll being staggered with relation to those upon another, with the edges of the discs of different rolls in register, a distributing roll common to all of said ductor rolls, inking rolls adapted to apply ink to the plates upon a plate cylinder, and distributing rolls intermediate said inking rolls and said first named distributing roll.

17. A printing machine embodying there-in a collecting cylinder having an offset printing surface thereon, an impression cylinder associated therewith, a plurality of plate cylinders each having a printing plate bearing a portion of a complete design in relief thereon, and an inking mechanism associated with each of said plate cylinders comprising an ink fount, a continuous ink fount roll associated therewith, a ductor roll cooperating with said ink fount roll and composed of a plurality of spaced discs, inking rolls adapted to apply ink to the plates upon a plate cylinder, and alternately arranged metallic and printer's roll composition distributing rolls adapted to receive stripes of ink from said ductor roll, work the ink and apply it in stripes to said inking roll.

18. A printing machine embodying there-in a collecting cylinder having an offset printing surface thereon, an impression cylinder associated therewith, a plurality of plate cylinders each having a printing plate bearing a portion of a complete design in

- relief thereon, and an inking mechanism associated with each of said plate cylinders comprising a plurality of ink founts adapted to each receive an ink of a different color, a continuous ink fount roll associated with each of said founts, ductor rolls associated with said ink fount rolls, respectively each consisting of a plurality of spaced discs, the discs upon one roll being staggered with relation to those upon another, with the edges of the discs of different rolls in register, a distributing roll common to all of said ductor rolls, inking rolls adapted to apply ink to the plates upon a plate cylinder, and distributing rolls intermediate said inking rolls and said first named distributing roll, said distributing rolls being alternately of metal and of printer's roll composition.
19. A printing machine embodying therein a collecting cylinder having an offset printing surface thereon, an impression cylinder associated therewith, a plurality of plate cylinders each having a printing plate bearing a portion of a complete design in relief thereon, and an inking mechanism associated with each of said plate cylinders comprising an ink fount, a continuous ink fount roll associated therewith, a ductor roll cooperating with said ink fount roll and composed of a plurality of spaced discs, a plurality of pairs of inking rolls adapted to apply ink to the plates upon a plate cylinder, and distributing rolls adapted to receive stripes of ink from said ductor roll, work the ink and apply it in stripes to said inking rolls respectively.
20. A printing machine embodying therein a collecting cylinder having an offset printing surface thereon, an impression cylinder associated therewith, a plurality of plate cylinders each having a printing plate bearing a portion of a complete design in relief thereon, and an inking mechanism associated with each of said plate cylinders comprising a plurality of ink founts adapted to each receive an ink of a different color, a continuous ink fount roll associated with each of said founts, ductor rolls associated with said ink fount rolls respectively each consisting of a plurality of spaced discs, the discs upon one roll being staggered with relation to those upon another, with the edges of the discs of different rolls in register, a distributing roll common to all of said ductor rolls, a plurality of pairs of inking rolls adapted to apply ink to the plates upon a plate cylinder, and distributing rolls intermediate said inking rolls and said first named distributing roll, said distributing rolls being alternately of metal and of printer's roll composition.
21. A printing machine embodying therein a collecting cylinder having an offset printing surface thereon, an impression cylinder, a plurality of plate cylinders each having a cameo printing plate bearing a part of a complete design thereon and associated with said collecting cylinder, means operative upon each of said cylinders whereby it may be moved toward or from said collecting cylinder, means associated with each of said cylinders and adapted to apply power to said last named means acting upon said cylinder independently of the means operative upon the other cylinders, manually operative means connected with each of said last named means and adapted to simultaneously actuate same so as to make them inoperative to move said plate cylinders toward said collecting cylinder, or to restore said means to their normal operative relation thereto to permit the movement of said plate cylinders towards said collecting cylinder, and an inking mechanism associated with each of said plate cylinders.
22. A printing machine embodying therein a collecting cylinder having an offset printing surface thereon, an impression cylinder, a plurality of plate cylinders each having a cameo printing plate bearing a part of a complete design thereon and associated with said collecting cylinder, means operative upon each of said cylinders whereby it may be moved toward or from said collecting cylinder, means associated with each of said cylinders and adapted to apply power to said last named means acting upon said cylinder independently of the means operative upon the other cylinders, manually operative means connected with each of said last named means and adapted to simultaneously actuate same so as to make them inoperative to move said plate cylinders toward said collecting cylinder, or to restore said means to their normal operative relation thereto to permit the movement of said plate cylinders towards said collecting cylinder, means whereby said manually operative means may be made inoperative to restore any cylinder to its normal operative relation, and an inking mechanism associated with each of said plate cylinders.
23. A printing machine embodying therein a collecting cylinder having an offset printing surface thereon, an impression cylinder, a plurality of plate cylinders each having a cameo printing plate bearing a part of a complete design thereon and associated with said collecting cylinder, means operative upon each of said cylinders whereby it may be moved toward or from said collecting cylinder, means associated with each of said cylinders and adapted to apply power to said last named means acting upon said cylinder independently of the means operative upon the other cylinders, manually operative means connected with each of said last named means and adapted to

- simultaneously actuate same so as to make them inoperative to move said plate cylinders toward said collecting cylinder, or to restore said means to their normal operative 5 relation thereto to permit the movement of said plate cylinders towards said collecting cylinder, an inking mechanism associated with each of said plate cylinders, means whereby said impression cylinder may be 10 moved toward or from said collecting cylinder, means operative thereon and actuated in synchronism with the rotation of said collecting cylinder, whereby said last named means may be actuated, and operative connections 15 between said last named means and said manually operative means, whereby the impression cylinder may receive movement, simultaneously with similar movements of said plate cylinders, toward and from said 20 collecting cylinder.
24. A printing machine embodying therein a collecting cylinder having an offset printing surface thereon, an impression cylinder, a plurality of plate cylinders each 25 having a cameo printing plate bearing a part of a complete design thereon and associated with said collecting cylinder, means operative upon each of said cylinders whereby it may be moved toward or from said collecting cylinder, studs, operative connections 30 between said studs and said means respectively, a cam associated with each of said plate cylinders, a rocking lever acted upon by each of said cams, a setting plate carried 35 by each of said levers, a hook and an impact member upon each of said plates and adapted to respectively co-operate with said studs, whereby with each rotation of said cams, said impact plates will act upon said studs 40 to impart movement to said cylinders away from said collecting cylinder, and said hooks acting upon said studs will impart movement to said cylinders toward said collecting cylinder, manually operative means connected with each of said plates adapted to simultaneously actuate same so as to move the hooks thereon out of, or into, the operative 45 relation to said studs and ensure the engagement of said impact plates with said studs, and an inking mechanism associated with each of said plate cylinders.
25. A printing machine embodying therein a collecting cylinder having an offset printing surface thereon, an impression cylinder, a plurality of plate cylinders each 55 having a cameo printing plate bearing a part of a complete design thereon and associated with said collecting cylinders, means operative upon each of said cylinders whereby it may be moved toward or from said collecting cylinder, studs, operative connections 60 between said studs and said means respectively, a cam associated with each of said plate cylinders, a rocking lever acted upon by each of said cams, a setting plate carried 65 upon by each of said cams, a setting plate
- carried by each of said levers, a hook and an impact member upon each of said plates and adapted to respectively cooperate with said studs, whereby with each rotation of said cams, said impact plates will act upon said 70 studs to impart movement to said cylinders away from said collecting cylinder, and said hooks acting upon said studs will impart movement to said cylinders toward said collecting cylinder, manually operative means connected with each of said plates adapted to simultaneously actuate same so as to move the hooks thereon out of, or into, the operative 75 relation to said studs and ensure the engagement of said impact plates with said studs, means operative upon each of said setting plates whereby any plate may be prevented from movement to engage the hook thereon with its co-operating stud independently of said manually operative 80 means, and an inking mechanism associated with each of said plate cylinders.
26. A printing machine embodying therein a collecting cylinder having an offset printing surface thereon, an impression cylinder, a plurality of plate cylinders each having a cameo printing plate bearing a part of a complete design thereon and associated with said collecting cylinder, means operative upon each of said cylinders whereby it may be moved toward or from said collecting cylinder, studs, operative connections 85 between said studs and said means respectively, a cam associated with each of said plate cylinders, a rocking lever acted upon by each of said cams, a setting plate carried 90 by each of said levers, a hook and an impact member upon each of said plates and adapted to respectively co-operate with said studs, whereby with each rotation of said cams, said impact plates will act upon said studs to impart movement to said cylinders away from said collecting cylinder, and said hooks acting upon said studs will impart movement to said cylinders toward said collecting cylinder, bell crank levers adjacent each of said setting plates and having one arm thereof slidably and pivotally mounted in relation to said plates respectively, a spider, a rod connected with one of the arms 95 thereof, manually controllable means whereby said rod may be used to impart rotary movement to said spider in either direction, links connected with different arms of said spider and slidably connected with one arm of said bell crank levers respectively, springs acting upon opposite sides of said last named arm and said rods whereby said rods may be moved in either direction independently of said bell crank levers, whereby movement 100 to said bell crank levers for imparting movement to said setting plates with relation to said studs, is imparted thereto through said springs, and an inking mechanism associated with each of said plate cylinders.

27. A printing machine embodying there-in a collecting cylinder having an offset printing surface thereon, an impression cylinder, a plurality of plate cylinders each having a cameo printing plate bearing a part of a complete design thereon and associated with said collecting cylinder, means operative upon each of said cylinders whereby it may be moved toward or from said collecting cylinder, studs, operative connections between said studs and said means respectively, a cam associated with each of said plate cylinders, a rocking lever acted upon by each of said cams, a setting plate carried by each of said levers, a hook and an impact member upon each of said plates and adapted to respectively co-operate with said studs, whereby with each rotation of said cams, said impact plates will act upon said studs to impart movement to said cylinders away from said collecting cylinder, and said hooks acting upon said studs will impart movement to said cylinders toward said collecting cylinder, bell crank levers adjacent each of said setting plates and having one arm thereof slidably and pivotally mounted in relation to said plates respectively, a spider, a rod connected with one of the arms thereof, manually controllable means whereby said rod may be used to impart rotary movement to said spider in either direction, links connected with different arms of said spider and slidably connected with one arm of said bell crank levers respectively, springs acting upon opposite sides of said last named arm and said rods whereby said rods may be moved in either direction independently of said bell crank levers, whereby movement of said bell crank levers for imparting movement to said setting plates with relation to said studs, is imparted thereto through said springs, an abutment upon each of said bell crank levers, a dog adapted to co-operate therewith, whereby movement of said levers in one direction under the control of said springs, is prevented, and an inking mechanism associated with each of said plate cylinders.

28. A printing machine embodying there-in a collecting cylinder having an offset printing surface thereon, an impression cylinder, a plurality of plate cylinders each having a cameo printing plate bearing a part of a complete design thereon and associated with said collecting cylinder, means operative upon each of said cylinders whereby it may be moved toward or from said collecting cylinder, means associated with each of said cylinders and adapted to apply power to said last named means acting upon said cylinder independently of the means operative upon the other cylinders, manually operative means connected with each of said last named means and adapted to simultaneously actuate same so as to make them in-operative to move said plate cylinders toward said collecting cylinder, or to restore said means to their normal operative relation thereto to permit the movement of said plate cylinders towards said collecting cylinder, an inking mechanism associated with each of said plate cylinders, means whereby said impression cylinder may be moved toward or from said collecting cylinder, means operative thereon and actuated in synchronism with the rotation of said collecting cylinder, whereby said last named means may be actuated, operative connections between said last named means and said manually operative means, whereby the impression cylinder may receive movement, simultaneously with similar movements of said plate cylinders, toward and from said collecting cylinder, and manually operative means independent of said first named manually operative means whereby the means operative upon said impression cylinder may be actuated to impart movement to said cylinder toward or from said collecting cylinder independently of said first named manually operative means.

29. A printing machine embodying there-in a collecting cylinder having an offset printing surface thereon, an impression cylinder, a plurality of plate cylinders each having a cameo printing plate bearing a part of a complete design thereon and associated with said collecting cylinder, means operative upon each of said cylinders whereby it may be moved toward or from said collecting cylinder, studs, operative connections between said studs and said means respectively, a cam associated with each of said plate cylinders, a rocking lever acted upon by each of said cams, a setting plate carried by each of said levers, a hook and an impact member upon each of said plates and adapted to respectively co-operate with said studs, whereby with each rotation of said cams, said impact plates will act upon said studs to impart movement to said cylinders away from said collecting cylinder, and said hooks acting upon said studs will impart movement to said cylinders toward said collecting cylinder, bell crank levers adjacent each of said setting plates and having one arm thereof slidably and pivotally mounted in relation to said plates respectively, a spider, a rod connected with one of the arms thereof, manually controllable means whereby said rod may be used to impart rotary movement to said spider in either direction, links connected with different arms of said spider and slidably connected with one arm of said bell crank levers respectively, springs acting upon opposite sides of said last named arm and said rods whereby said rods may be moved in either direction independently of said bell crank levers, whereby movement to said bell crank

- levers for imparting movement to said setting plates with relation to said studs, is imparted thereto through said springs, an inking mechanism associated with each of 5 said plate cylinders, means whereby said impression cylinder may be moved toward or from said collecting cylinder, means operative thereon and actuated in synchronism with the rotation of said collecting cylinder, 10 whereby said last named means may be actuated, operative connections between said last named means and said manually operative means, whereby the impression cylinder may receive movement, simultaneously with 15 similar movements of said plate cylinders, toward and from said collecting cylinder, and manually operative means independent of said first named manually operative means whereby the means operative upon 20 said impression cylinder may be actuated to impart movement to said cylinder toward or from said collecting cylinder independently of said first named manually operative means.
- 25 30. A printing machine embodying there-in a collecting cylinder having an offset printing surface thereon, an impression cylinder, a plurality of plate cylinders each having a cameo printing plate bearing a 30 part of a complete design thereon and associated with said collecting cylinder, means operative upon each of said cylinders whereby it may be moved toward or from said collecting cylinder, means associated with each of said cylinders and adapted to apply power to said 35 last named means acting upon said cylinder independently of the means operative upon the other cylinders, manually operative means connected with 40 each of said last named means and adapted to simultaneously actuate same so as to make them inoperative to move said plate cylinders toward said collecting cylinder, or to restore said means to their normal operative relation thereto to permit the movement of said plate cylinders towards said collecting cylinder, an inking mechanism associated with each of said plate cylinders, means whereby said impression cylinder 45 may be moved toward or from said collecting cylinder, a plate cylinder associated with said impression cylinder, an inking mechanism co-operating therewith, means whereby said last named plate cylinder may receive movement toward and from said collecting cylinder simultaneously with the 50 same movements of said impression cylinder, means operative thereon, and upon the means for imparting movement to the plate cylinder associated with said impression cylinder, and actuated in synchronism with the rotation of said collecting cylinder, whereby said last named means may be actuated, operative connections between said last named means and said manually operative means, whereby the impression cylinder may receive movement, simultaneously with 55 similar movements of said plate cylinders, toward and from said collecting cylinder, and manually operative means independent of said first named manually operative means whereby the means operative upon said impression cylinder and the plate cylinder associated therewith may be actuated to impart movement to said impression cylinder and said plate cylinder in a direction toward or from said collecting cylinder independently of the means controlled by said first named manually operative means.
- 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

ative means, whereby the impression cylinder may receive movement, simultaneously with similar movements of said plate cylinders, toward and from said collecting cylinder.

31. A printing machine embodying therein a collecting cylinder having an offset printing surface thereon, an impression cylinder, a plurality of plate cylinders each having a cameo printing plate bearing a part of a complete design thereon and associated with said collecting cylinder, means operative upon each of said cylinders whereby it may be moved toward or from said collecting cylinder, means associated with each of said cylinders and adapted to apply power to said last named means acting upon said cylinder independently of the means operative upon the other cylinders, manually operative means connected with each of said last named means and adapted to simultaneously actuate same so as to make them inoperative to move said plate cylinders toward said collecting cylinder, or to restore said means to their normal operative relation thereto to permit the movement of said plate cylinders towards said collecting cylinder, an inking mechanism associated with each of said plate cylinders, means whereby said impression cylinder may be moved toward or from said collecting cylinder, a plate cylinder associated with said impression cylinder, an inking mechanism co-operating therewith, means whereby said last named plate cylinder may receive movement toward and from said collecting cylinder simultaneously with the same movements of said impression cylinder, means operative thereon, and upon the means for imparting movement to the plate cylinder associated with said impression cylinder, and actuated in synchronism with the rotation of said collecting cylinder, whereby said last named means may be actuated, operative connections between said last named means and said manually operative means, whereby the impression cylinder may receive movement, simultaneously with similar movements of said plate cylinders, toward and from said collecting cylinder, and manually operative means independent of said first named manually operative means whereby the means operative upon said impression cylinder and the plate cylinder associated therewith may be actuated to impart movement to said impression cylinder and said plate cylinder in a direction toward or from said collecting cylinder independently of the means controlled by said first named manually operative means.

32. A printing machine embodying therein a collecting cylinder having an offset printing surface thereon, an impression cylinder, a plurality of plate cylinders each having a cameo printing plate bearing a part

of a complete design thereon and associated with said collecting cylinder, means operative upon each of said cylinders whereby it may be moved toward or from said collecting cylinder, studs, operative connections between said studs and said means respectively, a cam associated with each of said plate cylinders, a rocking lever acted upon by each of said cams, a setting plate carried by each of said levers, a hook and an impact member upon each of said plates and adapted to respectively co-operate with said studs, whereby with each rotation of said cams, said impact plates will act upon said studs to impart movement to said cylinders away from said collecting cylinder, and said hooks acting upon said studs will impart movement to said cylinders toward said collecting cylinder, bell crank levers adjacent each of said setting plates and having one arm thereof slidably and pivotally mounted in relation to said plates respectively, a spider, a rod connected with one of the arms thereof, manually controllable means whereby said rod may be used to impart rotary movement to said spider in either direction, links connected with different arms of said spider and slidably connected with one arm of said bell crank levers respectively, springs acting upon opposite sides of said last named arm and said rods whereby said rods may be moved in either direction independently of said bell crank levers, whereby movement to said bell crank levers for imparting movement to said setting plates with relation to said studs, is imparted thereto through said springs, an inking mechanism associated with each of said plate cylinders, a plate cylinder associated with said impression cylinder, an inking mechanism associated therewith, means adapted to impart simultaneous and similar movement to said impression cylinder and the plate cylinder associated therewith, an oscillatory plate, links connecting said plate with said last named means respectively, studs carried by said plate upon opposite sides of its pivotal point, a thrust member adapted to co-operate with either of said studs, a plurality of cams carried by said collecting cylinder, a bell crank lever acted upon by said cams and connected with said thrust member, a bell crank lever, a link connecting one of the arms thereof with said spider, a rod connected with said thrust member and slidably mounted in the other arm of said bell crank lever, and springs engaging opposite sides of said last named arm and said rod, whereby movement of said last named bell crank lever and said thrust member will be applied through said springs substantially simultaneously with the actuation of said setting plates.

33. A printing machine embodying therein a collecting cylinder having an offset printing surface thereon, an impression cylinder, a plurality of plate cylinders each having a cameo printing plate bearing a part of a complete design thereon and associated with said collecting cylinder, means operative upon each of said cylinders whereby it may be moved toward or from said collecting cylinder, studs, operative connections between said studs and said means respectively, a cam associated with each of said plate cylinders, a rocking lever acted upon by each of said cams, a setting plate carried by each of said levers, a hook and an impact member upon each of said plates and adapted to respectively co-operate with said studs, whereby with each rotation of said cams, said impact plates will act upon said studs to impart movement to said cylinders away from said collecting cylinder, and said hooks acting upon said studs will impart movement to said cylinders toward said collecting cylinder, bell crank levers adjacent each of said setting plates and having one arm thereof slidably and pivotally mounted in relation to said plates respectively, a spider, a rod connected with one of the arms thereof, manually controllable means whereby said rod may be used to impart rotary movement to said spider in either direction, links connected with different arms of said spider and slidably connected with one arm of said bell crank levers respectively, springs acting upon opposite sides of said last named arm and said rods whereby said rods may be moved in either direction independently of said bell crank levers, whereby movement to said bell crank levers for imparting movement to said setting plates with relation to said studs, is imparted thereto through said springs, an inking mechanism associated with each of said plate cylinders, a plate cylinder associated with said impression cylinder, an inking mechanism associated therewith, means adapted to impart simultaneous and similar movement to said impression cylinder and the plate cylinder associated therewith, an oscillatory plate, links connecting said plate with said last named means respectively, studs carried by said plate upon opposite sides of its pivotal point, a thrust member adapted to co-operate with either of said studs, a plurality of cams carried by said collecting cylinder, a bell crank lever acted upon by said cams and connected with said thrust member, a bell crank lever, a link connecting one of the arms thereof with said spider, a rod connected with said thrust member and slidably mounted in the other arm of said bell crank lever, and springs engaging opposite sides of said last named arm and said rod, whereby movement of said last named bell crank lever and said thrust member will be applied through said springs substantially simultaneously with the actuation of said setting plates, a crank shaft, and operative connec-

- tions between said crank shaft and said thrust member, whereby said thrust member may be actuated independently of said spider.
5. 34. A printing machine embodying there-in a collecting cylinder having an offset printing surface thereon, an impression cyl- 70 nder associated therewith, a plurality of plate cylinders each having a printing plate bearing a portion of a complete design in relief thereon, and an inking mechanism as- 75 sociated with each of said plate cylinders comprising inking rolls adapted to apply ink to the plates upon a plate cylinder, distrib- 80 uted rolls co-operating therewith, means whereby ink in a plurality of adjoining register- 85 ing stripes is applied to said distribut- 90 ing rolls, means whereby axial vibratory movement may be imparted to some of said 95 distributing rolls, whereby adjoining edges of the ink applied to said distributing rolls, is blended, and independently operative means associated with each inking mechanism for imparting movement to said last 100 named distributing rolls.
35. A printing machine embodying there-in a collecting cylinder having an offset printing surface thereon, an impression cyl- 105 nder associated therewith, a plurality of plate cylinders each having a printing plate bearing a portion of a complete design in relief thereon, and an inking mechanism as- 110 sociated with each of said plate cylinders comprising inking rolls adapted to apply ink to the plates upon a plate cylinder, distrib- 115 uted rolls co-operating therewith, means whereby ink in a plurality of adjoining register- 120 ing stripes is applied to said distribut- 125 ing rolls, a crank disc associated with each of said inking mechanisms, operative connections between said crank disc and some of said distributing rolls, whereby adjoining edges of the ink applied to said dis- 130 tributing rolls, is blended, and means where- 135 by the crank of said disc may be adjusted to be concentric with the axis of the disc, or eccentrically thereto in a varying degree, whereby said crank disc and said connec- 140 tions may be made inoperative to impart vi- 145 bratory movement to said rolls, or to impart vibratory movements thereto to a varying extent.
36. A printing machine embodying there-in a collecting cylinder having an offset print- 150 ing surface thereon, an impression cylinder associated therewith, a plurality of plate cylinders each having a printing plate bearing a portion of a complete design in relief thereon, and an inking mechanism as- 155 sociated with each of said plate cylinders comprising inking rolls adapted to apply ink to the plates upon a plate cylinder, distrib- 160 uted rolls co-operating therewith, means whereby ink in a plurality of adjoining reg- 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

in a collecting cylinder having a planographic printing surface thereon, a plurality of plate cylinders each having a cameo printing plate thereon, means whereby said plate cylinders may be moved into and out of the operative relation to said collecting cylinder, an inking mechanism associated with each of said plate cylinders, embodying therein a plurality of ink founts, an oscillatory ductor roll associated with each fount, a train of distributing rolls to which said ductor rolls respectively apply ink from said founts, and inking rolls receiving ink from said distributing rolls and applying it to the plates upon said plate cylinders, means whereby movement is imparted to said inking and distributing rolls simultaneously with the movement of said printing plate cylinders, while maintaining engagement of the inking rolls with the plates thereon, and means operative upon said ductor rolls independently of the movement of said inking and distributing rolls with relation to said plate cylinder, whereby they may be held out of the operative relation to their respective ink founts.

40. A printing machine embodying therein a collecting cylinder having a planographic printing surface thereon, a plurality of plate cylinders each having a cameo printing plate thereon, means whereby said plate cylinders may be moved into and out of the operative relation to said collecting cylinder, an inking mechanism associated with each of said plate cylinders, embodying therein a plurality of ink founts, an oscillatory ductor roll associated with each fount, a train of distributing rolls to which said ductor rolls respectively supply ink from said founts, and inking rolls receiving ink from said distributing rolls and applying it to the plates upon said plate cylinders, means whereby movement is imparted to the said inking and distributing rolls simultaneously with the movement of said printing plate cylinders, while maintaining engagement of the inking rolls with the plates thereon, means operative upon said ductor rolls independently of the movement of said inking and distributing rolls with relation to said plate cylinder, whereby they may be held out of the operative relation to their respective ink founts, and operative connections between the means for moving said plate cylinders with relation to said collecting cylinder and said last named means, whereby the operative effect of said ductor rolls will be determined by the relation of said plate cylinders to said collecting cylinder.

41. A printing machine embodying therein a collecting cylinder having a planographic printing surface thereon, a plurality of plate cylinders each having a cameo printing plate thereon, means whereby said plate cylinders may be moved into and out of the operative relation to said collecting cylinder, an inking mechanism associated with each of said plate cylinders, embodying therein a plurality of ink founts, an oscillatory ductor roll associated with each fount, a train of distributing rolls to which said ductor rolls respectively apply ink from said founts, and inking rolls receiving ink from said distributing rolls and applying it to the plates upon said plate cylinders, means whereby movement is imparted to the said inking and distributing rolls simultaneously with the movement of said printing plate cylinders, while maintaining engagement of the inking rolls with the plates thereon, oscillatory frames carrying said ductor rolls respectively, springs acting upon said frames having a normal tendency to move said ductor rolls into engagement with their co-operating ink fount rolls, a cam, a bell crank lever, one arm of which is operative upon one of said frames, means operative upon the other of said frames, a link connecting the other arm of said bell crank lever and said last named means, whereby said frames receive similar movement from

plate cylinders may be moved into and out of the operative relation to said collecting cylinder, an inking mechanism associated with each of said plate cylinders, embodying therein a plurality of ink founts, an oscillatory ductor roll associated with each fount, a train of distributing rolls to which said ductor rolls respectively apply ink from said founts, and inking rolls receiving ink from said distributing rolls and applying it to the plates upon said plate cylinders, means whereby movement is imparted to said inking and distributing rolls simultaneously with the movement of said printing plate cylinders, while maintaining engagement of the inking rolls with the plates thereon, oscillatory frames carrying said ductor rolls respectively, springs acting upon said frames having a normal tendency to move said ductor rolls into engagement with their co-operating ink fount rolls, a cam, a bell crank lever, one arm of which is operative upon one of said frames, means operative upon the other of said frames, a link connecting the other arm of said bell crank lever and said last named means, whereby said frames receive similar movement from

42. A printing machine embodying therein a collecting cylinder having a planographic printing surface thereon, a plurality of plate cylinders each having a cameo printing plate thereon, means whereby said plate cylinders may be moved into and out of the operative relation to said collecting cylinder, an inking mechanism associated with each of said plate cylinders, embodying therein a plurality of ink founts, an oscillatory ductor roll associated with each fount, a train of distributing rolls to which said ductor rolls respectively apply ink from said founts, and inking rolls receiving ink from said distributing rolls and applying it to the plates upon said plate cylinders, means whereby movement is imparted to the said inking and distributing rolls simultaneously with the movement of said printing plate cylinders, while maintaining engagement of the inking rolls with the plates thereon, oscillatory frames carrying said ductor rolls respectively, springs acting upon said frames having a normal tendency to move said ductor rolls into engagement with their co-operating ink fount rolls, a cam, a bell crank lever, one arm of which is operative upon one of said frames, means operative upon the other of said frames, a link connecting the other arm of said bell crank lever and said last named means, whereby said frames receive similar movement from

said cam, a crank shaft, a swinging cam adapted to engage said link and prevent a full return movement of said bell crank lever under the control of said cam and said springs, and operative connections between said crank shaft and said swinging cam.

43. A printing machine embodying therein a collecting cylinder having a planographic printing surface thereon, a plurality of plate cylinders each having a cameo printing plate thereon, means whereby said plate cylinders may be moved into and out of the operative relation to said collecting cylinder, an inking mechanism associated with each of said plate cylinders, embodying therein a plurality of ink founts, an oscillatory ductor roll associated with each fount, a train of distributing rolls to which said ductor rolls respectively apply ink from said founts, and inking rolls receiving ink from said distributing rolls and applying it to the plates upon said plate cylinders, means whereby movement is imparted to said inking and distributing rolls simultaneously with the movement of said printing plate cylinders, while maintaining engagement of the inking rolls with the plates thereon, oscillatory frames carrying said ductor rolls respectively, springs acting upon said frames having a normal tendency to move said ductor rolls into engagement with their co-operating ink fount rolls, a cam, a bell crank lever, one arm of which is operative upon one of said frames, means operative upon the other of said frames, a link connecting the other arm of said bell crank lever and said last named means, whereby said frames receive similar movement from said cam, adjustable impact screws carried by said frames respectively and adapted to be engaged by said bell crank lever and said means, whereby the movement of said frames may be regulated to develop the desired engaging relations of the ductor roll with its co-operating distributing roll and the roll of its co-operating ink fount, and means adapted to prevent a full return movement of said bell crank lever whereby said frames will be maintained in a position to prevent the engagement of the ductor rolls carried thereby with the respective ink fount rolls.

45. A printing machine embodying therein a collecting cylinder having a planographic printing surface thereon, a plurality of plate cylinders each having a cameo printing plate thereon, means whereby said plate cylinders may be moved into and out of the operative relation to said collecting cylinder, an inking mechanism associated with each of said plate cylinders, embodying therein a plurality of ink founts, an oscillatory ductor roll associated with each fount, a train of distributing rolls to which said ductor rolls respectively apply ink from said founts, and inking rolls receiving ink from said distributing rolls and applying it to the plates upon said plate cylinders, means whereby movement is imparted to said inking and distributing rolls simultaneously with the movement of said printing plate cylinders, while maintaining engagement of the inking rolls with the plates thereon, oscillatory frames carrying said ductor rolls respectively, springs acting upon said frames having a normal tendency to move said ductor rolls into engagement with their co-operating ink fount rolls, a cam, a bell crank lever, one arm of which is operative upon one of said frames, means operative upon the other of said frames, a link connecting the other arm of said bell crank lever and said last named means, whereby said frames receive

ing ink from said distributing rolls and applying it to the plates upon said plate cylinders, means whereby movement is imparted to said inking and distributing rolls simultaneously with the movement of said printing plate cylinders, while maintaining engagement of the inking rolls with the plates thereon, oscillatory frames carrying said ductor rolls respectively, springs acting upon said frames having a normal tendency to move said ductor rolls into engagement with their co-operating ink fount rolls, a cam, a bell crank lever, one arm of which is operative upon one of said frames, means operative upon the other of said frames, a link connecting the other arm of said bell crank lever and said last named means, whereby said frames receive similar movement from said cam, adjustable impact screws carried by said frames respectively and adapted to be engaged by said bell crank lever and said means, whereby the movement of said frames may be regulated to develop the desired engaging relations of the ductor roll with its co-operating distributing roll and the roll of its co-operating ink fount, and means adapted to prevent a full return movement of said bell crank lever whereby said frames will be maintained in a position to prevent the engagement of the ductor rolls carried thereby with the respective ink fount rolls.

45. A printing machine embodying therein a collecting cylinder having a planographic printing surface thereon, a plurality of plate cylinders each having a cameo printing plate thereon, means whereby said plate cylinders may be moved into and out of the operative relation to said collecting cylinder, an inking mechanism associated with each of said plate cylinders, embodying therein a plurality of ink founts, an oscillatory ductor roll associated with each fount, a train of distributing rolls to which said ductor rolls respectively apply ink from said founts, and inking rolls receiving ink from said distributing rolls and applying it to the plates upon said plate cylinders, means whereby movement is imparted to said inking and distributing rolls simultaneously with the movement of said printing plate cylinders, while maintaining engagement of the inking rolls with the plates thereon, oscillatory frames carrying said ductor rolls respectively, springs acting upon said frames having a normal tendency to move said ductor rolls into engagement with their co-operating ink fount rolls, a cam, a bell crank lever, one arm of which is operative upon one of said frames, means operative upon the other of said frames, a link connecting the other arm of said bell crank lever and said last named means, whereby said frames receive

similar movement from said cam, means adapted to prevent a full return movement of said bell crank lever whereby said frames will be maintained in a position to prevent the engagement of the ductor rolls carried thereby with the respective ink fount rolls, an ink roll in each of said founts, an intermittently operative pawl and ratchet mechanism for turning said rolls respectively, and a projection carried by

each of said frames adapted to engage the pawl of said mechanism.

In witness whereof I have hereunto affixed my signature, in the presence of two subscribing witnesses, this 1st day of February, 1922.

FRANK C. MARQUARDT.
